ABSTRACT OF THE DISCLOSURE

A multiple-digit static counter each of whose stages has main and auxiliary stores and which is controlled by counting signals and auxiliary counting signals, the latter being staggered with respect to and timely spaced from the former. The instants at which the main stores, at whose outputs there appears the count of the respective digit, are set and erased, are controlled by the respective auxiliary store which has different circuit conditions at the two instants and, in addition, by the counter stage of the preceding digit and/or by the counting and/or auxiliary counting signals. As a result, there is built into the counter a tolerance for differences in the characteristics of the semiconductor elements forming part of the counter, in that differences in the switching times of the individual circuit components will not cause errors.

The present invention relates to a static counter.

In recent years, electronic counting has become increasingly more important and is used, to a very large extent, in the measuring, controlling and regulating arts. The hardware involved is in the nature of electronic counters whose function it is to count serially, i.e., successively, applied signals, generally in the form of pulses, and to put out the count in parallel representation. That is to say, the incoming pulses arrive one after the other, or serially, while all of the digits of the counted result appear simultaneously at the output of the counter, i.e., in timed parallel relationship. In the case of binary counters, for example, each binary digit has a counter stage associated with it.

Most of the electronic counters which have been developed operate on the dynamic principle. The individual counter stages of dynamic counters consist of bistable circuits which are capacitatively coupled with each other. The input signals which excite these stages have to meet certain requirements, particularly insofar as the steepness of the flanks is concerned. In addition to requiring pulses of special configuration, dynamic counters have the additional drawback that they are susceptible to external disturbances.

There exist other counters which incorporate galvanically coupled step-down stages, whose first stage is controlled by the counting signal and its negation, and which puts out signals which have been stepped down in a 2:1 ratio. The output signals are applied to further stages where they are again stepped down in a ratio of 2:1. Such counters have the drawback that the changeover from one circuit condition to the other does not always take place reliably, due to the presence of discontinuities. Instead the counter stages may assume the incorrect circuit condition.

It is, therefore, the object of the present invention to provide a counter which overcomes the above-mentioned drawbacks, and the present invention therefore resides in a trouble-free static counter incorporating

2

galvanically coupled counter stages, which counter has no discontinuities, and which counter is, moreover, substantially proof against external interference.

It is another object of the present invention to provide 5 a counter which can readily be so modified that it can be preset to a given binary number.

It is still another object of the present invention to provide a counter which, with few additional components, can be converted into a decimal counter, it being another 10 object of the present invention that such a decimal counter, too, can be modified so as to enable it to be preset to any desired decimal number.

It is a further object of the present invention to provide counters of the above type, all of which are adapted 15 to count forward or backward, and, moreover, are susceptible to being so arranged that all of the counter stages are alike, thereby enabling use of simple modular units.

With the above objects in view, the present invention relates to a static counter which is able to count forward 20 or backward and is capable of being preset to a desired binary number, which counter can be converted to a decimal counter which is able to count forward or backward and can, if desired, be made capable of being preset to a desired decimal number, which counter, moreover, 25 can have applied to it counting signals and auxiliary counting signals of any shape, the auxiliary counting signals being displaced, with respect to time, relative to the counting signals, i.e., the counting signals and the auxiliary counting signals are timely spaced from each other. 30 More particularly, the present invention resides in the fact that the counter stage of each binary digit comprises (1) a main storage unit which puts out the counted result of the respective binary digit and (2) an auxiliary storage unit; the two instants at which the setting (i.e., storing) and the resetting (i.e., erasing) of the main storage unit occur are fixed by the respective auxiliary storage unit which, at these instants of time, has different circuit conditions (i.e., either 0 or L, where L=binary 1) and by at least one counter stage of the preceding binary 35 stages or a counting signal or an auxiliary counting signal.

According to a further feature of the invention, the main storage unit of each binary digit changes its circuit condition during the counting operation only at the 40 instant of a counting signal (t_1), and the corresponding auxiliary storage unit changes its condition at the instant of an auxiliary counting signal (t_2) or a counting signal (t_1), but not at the same instant as the main storage unit. In practice, the main and auxiliary storage units 45 will each have at least two logic circuits, and according to a further feature of the present invention, the input stages of the auxiliary and main storage units are AND-circuits. It is of advantage if the auxiliary storage unit has at least two input AND-circuits and the main storage unit has at least three input AND-circuits each of which controls an OR/NOT-circuit whose output, in 50 turn, is connected to a NOT-circuit.

According to a further feature, the output of the co-operating auxiliary storage unit changes its condition 55 only once while the output signal of the main storage unit is L. It is advantageous if the number of times which the output signal of the corresponding auxiliary storage unit changes its state is an odd number of times, and is equal to at least $2^n - 1$ ($n=0, 1, 2, \dots$) while the output signal of the main storage unit of the nth counter stage (whose digital value is $2^n - 1$) is L.

According to a further feature, the auxiliary storage unit of the lowest order binary digit produces signals in dependence on the count (0 or L) of the main storage unit of the same binary digit, and the auxiliary storage units in the following binary digits produce signals in de-

pendence on the count of the main storage unit of the same binary digit and the auxiliary storage unit of the next-lower binary digit, which signals control the main storage unit of the same binary digit and the main and auxiliary storage units of the next higher binary digit, and which signals are of such form that, with their help, the corresponding main storage units form signal combinations corresponding to the selected binary code. It is advantageous if the main storage units of the counter stages have the logical functions

$$(t_1 \& \bar{H}_0) v(\bar{A}_0 \& \bar{H}_0) v(A_0 \& \bar{t}_1) = A_0$$

$$(t_1 \& H_{n-1} \& \bar{H}_n) v(A_n \& \bar{H}_n) v(A_n \& \bar{t}_1) = A_n$$

and if the auxiliary storage units of the counter stages having logical functions

$$(t_2 \& A_0) v(H_0 \& A_0) v(H_0 \& \bar{t}_2) = H_0$$

$$(t_2 \& A_n) v(H_n \& H_{n-1}) = H_n$$

where

t_1 =the counting signal which controls the main storage units,

t_2 =the auxiliary counting signal which controls the auxiliary storage units,

A =the output signal of a main storage unit,

H =the output signal of an auxiliary storage unit, and $n=1, 2, 3, \dots$

According to yet another feature of the present invention, an erase or reset signal is applied to the counter stages. It is advantageous if this erase signal is composed of at least two erase signals, for example, according to the logic function $t_1 v t_2 = 1$, so that counters which are a part of an arrangement to which further storage units belong, can be erased independently of the storage units which do not belong to the counters. This can be done, for example, by applying to the storage units of the counter the composite erase reset signal 1 or $\bar{1}$, depending on the formation of the signal, while, for example t_1 or $\bar{t}_1$ is applied to the other storage units of the arrangement.

According to a further feature, the main storage units of the counter stages have the logical function

$$(t_1 \& \bar{H}_0 \& \bar{t}_1) v(A_0 \& \bar{H}_0 \& \bar{t}_1) v(A_0 \& \bar{t}_1 \& \bar{1}) = A_0$$

$$(t_1 \& H_{n-1} \& \bar{H}_n) v(A_n \& \bar{H}_n \& \bar{t}_1) v(A_n \& \bar{t}_1 \& \bar{1}) = A_n$$

and the auxiliary storage units of the counter have the logical function

$$(t_2 \& A_0) v(H_0 \& A_0 \& \bar{t}_2) v(H_0 \& \bar{t}_2 \& \bar{1}) = H_0$$

$$(t_2 \& A_n) v(H_n \& H_{n-1}) = H_n$$

It is advantageous if there is introduced into the counter stage of the lowest order binary digit a counting command signal with the help of which it is decided whether the counter is to count the counting signals. According to a further feature of the present invention, therefore, the main storage unit of the counter stage of the lowest binary digit has the logical switching function

$$(t_1 \& \bar{H}_0 \& \bar{t}_1 \& z) v(A_0 \& \bar{H}_0 \& \bar{t}_1) v(A_0 \& \bar{t}_1 \& \bar{1}) = A_0$$

and the corresponding auxiliary storage unit has the logical switching function

$$(t_2 \& A_0) v(H_0 \& A_0 \& \bar{t}_2 \& z) v(H_0 \& \bar{t}_2 \& \bar{1} \& z) = H_0$$

It is, furthermore, advantageous, if a "clear for counting" signal is applied to the counter stage of the lowest binary digit, which clear for counting signal is so synchronized by a counting command signal that may appear at any instant as to appear and disappear at the start of an auxiliary signal.

According to a further feature of the present invention, there is formed, from a counting command signal appearing at any time and with the help of a storage unit, a signal which, when $1=0$, is produced when the first counting signal following the counting command signal $=L$ appears, and which disappears when the erase command $1=L$ or when the first counting signal following the disappearance of the counting command signal appears; this

signal controls a further storage unit which is set with the first auxiliary counting signal appearing after the signal $z_1=L$, this storage unit being erased with the erase command signal $1=L$ or with the first auxiliary counting signal following the disappearance of the z_1 signal. It is of advantage if the storage unit for the signals has the logical function

$$(z \& t_1 \& \bar{1}) v(z_1 \& z \& \bar{1}) v(z_1 \& \bar{t}_1 \& \bar{1}) = z_1$$

$$(z_1 \& t_2) v(z_2 \& z_1) v(z_2 \& \bar{t}_2 \& \bar{1}) = z_2$$

According to a further feature of the present invention, the main storage unit of the lowest order binary digit has the logic function

$$(t_1 \& z_2 \& \bar{H}_0 \& 1) v(A_0 \& \bar{H}_0 \& \bar{t}_1) v(A_0 \& \bar{t}_1 \& \bar{1}) = A_0$$

and the corresponding auxiliary storage unit has the logic function

$$(t_2 \& A_0) v(H_0 \& z_2 \& A_0) v(H_0 \& z_2 \& \bar{t}_2) = H_0$$

It is of advantage if the counter stage of the lowest order binary digit is divided into two parts one of which corresponds to the remaining counter stages and the other of which is an input part. According to a further feature, therefore, the auxiliary storage unit of the lowest order binary digit has the logic function

$$(t_2 \& A_0) v(H_0 \& e) = H_0$$

where e is formed from the switching function

$$(z_2 \& A_0) v(z_2 \& \bar{t}_2) = e$$

or

$$\bar{z}_2 v(\bar{A}_0 \& t_2) = e$$

It is of advantage if at least two signals which, up to now, have been applied to all of the main or auxiliary storage units of the counter stages, are combined in a special supplementary circuit whose output signal replaces the control signals. According to a further feature of the present invention, therefore, the main storage units have the logic functions

$$(t_1 \& z_2 \& \bar{H}_0) v(A_0 \& \bar{H}_0 \& \bar{t}_1) v(A_0 \& t_1') = A_0$$

$$(t_1 \& H_{n-1} \& \bar{H}_n) v(A_n \& \bar{H}_n \& \bar{t}_1) v(A_n \& \bar{t}_1') = A_n$$

where

$$\bar{t}_1 \& \bar{t}_1' = \bar{t}_1$$

According to a further feature, the main storage units of the counter stages are controlled, following an erase command, by presetting signals in order to obtain a presetting of the counter to a given binary number. Therefore, each of the main storage units has associated with it a logic circuit which is controlled by the presetting signal and a "clear for presetting" signal. This logic circuit preferably has the function

$$(k_n \& f) n=0, 1, 2 \dots$$

According to a further feature, the preset clearing signal appears after the erasing and disappears with the clearing for counting, and reappears only after a further erasing. Preferably, a storage unit is provided for producing the clear for presetting signal, which storage unit has the logic function

$$1 v(m \& \bar{z}_2) = m$$

and forms a signal which controls a logic stage connected to the output of the storage unit which has a further input for the erase signal and itself has the logic function

$$(m \& \bar{1}) = f \text{ or } \bar{m} v 1 = f$$

and puts out the signal f .

According to a further feature by means of which the binary counter can be converted into a decimal counter, each decade consists of four binary counter stages, and within each decade a signal is fed back from the fourth counter stage to the second counter stage and a signal is

fed back from the fourth counter stage to the third counter stage, or a signal from the fourth counter stage is fed back to the second counter stage and a signal of the first counter stage is applied to the fourth counter stage. In practice, the signals needed for the decimal conversion replace the signals controlling the binary counter, or the signals needed for the decimal conversion are combined with the signals which, up to now, have controlled the binary counter, in separate logic circuits whose output signals replace the control signals used up to now, with the arrangement being such that the construction of the binary counter stages remains unchanged.

According to a further feature, the auxiliary storage units of the second and third counter stages have applied to them a further signal from the fourth counter stage. It is of advantage to provide the auxiliary storage units of the second and third counter stages each with a logic input stage, for the $(i+1)^{\text{th}}$ decade (value 10^i) has the logic function

$$(A_3^i \& t_2)$$

According to a further feature, the manner in which the auxiliary storage units of the second and third counter stages are controlled is modified, in comparison to the binary counter, in that the signal which, up to now, has controlled each counter stage is replaced by the output signal of a separate logic circuit in which the signal which up to now was the controlling signal is combined with a signal from the fourth counter stage. It is of advantage if the separate logic circuit for the second counter stage has the function

$$(A_1^i \vee A_3^i) = q_1^i \text{ or } \overline{A_1^i \& A_3^i} = q_1^i$$

and if the logic circuit for the third counter stage has the function

$$(A_2^i \vee A_3^i) = q_2^i \text{ or } \overline{A_2^i \& A_3^i} = q_2^i$$

According to a further feature, the main storage unit of the second counter stage has applied to it a signal from the fourth counter stage and the auxiliary storage unit of the fourth counter stage has applied to it a signal from the first counter stage. It is of advantage if there is additionally applied to the input stage of the main storage unit of the second counter stage of the decade (value 10^i) a signal from the auxiliary storage unit of the fourth counter stage, and if, in an input stage of the auxiliary storage unit of the fourth counter stage, the signal of the auxiliary storage unit of the preceding counter stage is replaced by the signal of the auxiliary storage unit of the first counter stage. According to a further feature of the present invention, therefore, one of the two signals which, up to now, have controlled the main storage unit of the second counter stage, is replaced by the output signal of a separate logic circuit in which the signal which, up to now, has controlled, is combined with a signal from the fourth counter stage, and the signal which controls the auxiliary storage unit of the fourth counter stage is replaced by a signal from the first counter stage. It is of advantage if the separate logic circuit for the second counter stage has the function

$$H_0^i \& \overline{H_3^i} = p_0^i \text{ or } \overline{H_0^i \vee H_3^i} = p_0^i$$

According to a further feature, the purpose of which is to allow presetting of the counter to any desired decimal number, presetting signals are applied to the main storage units of the counter stages. It is of advantage if the main storage units of the counter stages of the $(i+1)^{\text{th}}$ decade have associated with them a logic circuit which is controlled by a clear for presetting signal and a presetting signal. According to a further feature of the present invention, therefore, each of the main storage units has associated with it a supplementary component for the presetting, which component has the logic function

$$(k_n^i \& f)$$

$i=0, 1, 2 \dots$
 $n=0, 1, 2 \dots$

It is advantageous if the clear for presetting signal is the clear for presetting signal of the binary counter.

According to a further feature, the purpose of which is to permit the decimal counter to count backwards as well as forward, the outputs of the counter stages are connected to a converter. It is of advantage if the outputs of the converter put out the complement to the number 9.

Additional objects and advantages of the present invention will become apparent upon consideration of the following description when taken in conjunction with the accompanying drawings in which:

FIGURE 29a shows, schematically, the arrangement of luminous elements by means of which numerals, as illustrated in FIGURE 29b, can be represented, while FIGURE 29c contains a table showing the possible output combinations of a decade and the corresponding converted combinations according to FIGURE 29b.

FIGURES 30a and 30b are circuit diagrams of converters for the decimal counter of FIGURE 29.

FIGURE 31a contains a table showing the combination of signals within one decade.

FIGURES 31b and 31c are circuit arrangements for forming error signals.

Reference will now be made to the drawings.

Structure and operation of a binary counter

A reliably operating static counter requires, besides the signals t_1 which are to be counted, auxiliary counting signals t_2 which, as shown, for example, in FIGURE 1, are staggered or time-shifted with respect to the signals t_1 , i.e., the signals t_2 do not appear at the same time as the signals t_1 .

The binary counter requires a counter stage for each binary digit. Each counter stage requires two storage units, namely, a main storage unit and an auxiliary storage unit, which are set and erased by signals, i.e., which store signals and which clear the signals, only when certain conditions are met. The storage units are coupled galvanically. The storage units are set or erased only when the amplitude of the control signals applied to the storage units exceeds a predetermined value, the shape of the flanks of the signal pulses being of non consequence.

FIGURE 2a is a pulse diagram which shows the signals needed for controlling the counter, as well as the output signals of four counter stages. In order to keep FIGURE 2a reasonably simple, only the affirmed signals are shown (for example, only t_1 is shown, but not its negation t_1). Also for the sake of simplicity, the pulses are shown as square wave pulses. The signals can have the value 0 or L. In this as well as all other diagrams, the zero line or abscissa will be deemed to represent the value 0 while the lines overlying this abscissa line will be considered as representing the value L.

Upon the appearance of an erase signal $1=L$, the outputs A of the main storage units, as they are shown for example in FIGURE 5 at S_A , and the outputs H of the auxiliary storage units, shown in FIGURE 5 at S_H , are set to 0. When, after erasing, $1=0$, the counter is ready for operation.

The signals to be counted are indicated as t_1 , while the further, auxiliary signals needed to control the counter are indicated as t_2 . These signals are staggered, and there are time intervals between them, as shown.

The clear for counting signal z_2 , the signals t_1 being counted only when $z_2=L$. In practice, the signal z_2 is so synchronized that it can change only with the leading flank of an auxiliary counting signal t_2 . One embodiment of this will be explained below. The output of the main storage unit of the counter stage for the lowest order binary digit is indicated at A_0 , the output for the main

storage unit of higher order digits at A_1 , A_2 , and so on. Similarly, the outputs of the auxiliary storage units are indicated at H_0 , H_1 , H_2 , and so on. The indices 0, 1, 2 . . . represent the digital value 2^0 , 2^1 , 2^2 . . . of the

5 binary digits.

It will be seen that with each counting step 1, 2, 3 . . . the count indicated at the outputs A increases by one unit, i.e., the combination of 0 and L signals changes in accordance with the natural binary code. Thus, with the first signal $t_1(c_1)$ to be counted, the signal at output A_0 is L while the signals at outputs A_1 , A_2 , and so on, will each be 0. With the second counting signal $t_1(c_2)$, the output at A_0 becomes 0, the signal at A_1 becomes equal to L, and the signals at the outputs A_2 , A_3 , etc., remain at 0. The diagram shows the progress made up to and including the 23rd counting step, it being assumed that the count will not change during such durations as z_2 is equal to 0.

As already stated, auxiliary signals t_2 are needed in addition to the signals t_1 which signals t_2 are used for producing further signals H. The instants at which the H signals are stored and erased are so selected that, with the help of these signals, there will appear at the outputs A of the main storage units signal combinations corresponding to the natural binary code, and that the switching functions for the main as well as the auxiliary storage units will be as simple as possible.

In order that the main storage unit of the lowest order binary digit having the output A_0 will be set (stored) 20 upon the appearance of the first counting signal $t_1(c_1)$ and reset (erased) upon the appearance of the second counting signal $t_1(c_2)$, the two instants of time are distinguished by a second signal H_0 which is produced by an auxiliary storage unit which thus is in different circuit condition at the start and end of the signal A_0 . This auxiliary storage unit is set upon the appearance of the first auxiliary signal $t_2(d_1)$ while the output $A_0=L$, and erased with the following auxiliary signal $t_2(d_2)$ when A_0 is again equal to 0. There is thus obtained the following 25 switching function (the erasing signal 1 and the clear for counting signal z_2 being, for the time being not considered):

$$(t_1 \& H_0) v(A_0 \& H_0 \& t_1) = A_0 \quad (1)$$

$$(t_2 \& A_0) v(H_0 \& \overline{A_0} \& t_2) = H_0 \quad (2)$$

The output A_1 of the main storage unit of the binary digit 2^1 has to become L upon the appearance of the second counting signal (c_2) and 0 upon the appearance of the fourth counting signal (c_4) . At these instants $H_0=L$. These two instants of time are, in accordance with the present invention, distinguished from each other by a further signal H_1 which is formed by means of a further auxiliary storage unit $H_1=0$ at the beginning of A_1 and is equal to L at the end of A_1 , in which case it is advantageous, insofar as simplicity of switching function for the counter stage is concerned, if, for the duration of the third counting signal $t_1(c_3)$, the signal $H_1=0$.

The signal H_1 shown in the diagram fulfills these conditions. The signal H_1 is equal to L during the time intervals indicated at b_1 , b_2 . The switching function for the auxiliary storage unit which produces this signal is particularly simple. The auxiliary storage units for H_1 becomes, dominantly, set upon the appearance of a counting signal t_2 when $A_1=L$, and is erased with H_0 (this being the negation of H_0 , which is not shown). The switching function for the output signal of the main storage unit and the auxiliary storage unit of the binary digit 2^1 , without taking into consideration the erasing signal 1, is thus:

$$(t_1 \& H_0 \& \overline{H_1}) v(A_1 \& \overline{H_1} \& t_1) = A_1 \quad (3)$$

$$(t_2 \& A_1) v(H_1 \& H_0) = H_1 \quad (4)$$

In the response condition for A_1 , the t_1 in the first bracketed term can be replaced by $\overline{A_0}$. The switching

function for H_1 can also be modified in such a manner that, during the time interval indicated at b_1 , H_1 remains equal to 0, for example, by replacing the first bracketed term of the function (4) by $(t_2 \& A_1 \& H_0 \& A_0)$. This, however, increases the complexity of the circuit arrangement.

It is also possible, in the manner described above, to provide counter stages with the help of signals which appear and disappear at different instants of time. For example, it is possible to select a signal H_1 which becomes equal to L at the same instant as the illustrated signal H_1 but which is not erased until after the illustrated signal $A_1=0$ (such a signal is then, for example, during the third counting signal (c_3), equal to L). Alternatively, the signal H_1 can be so selected that it becomes equal to L at the start of A_1 and equal to 0 at the end of A_1 . In both cases, the switching functions for the main and auxiliary storage units become more complicated. The next signals A_2 and H_2 , A_3 and H_3 , are formed by main and auxiliary storage units, as described above in conjunction with the signals A_1 and H_1 . Again, the counting signals t_1 and the auxiliary counting signals t_2 are applied to the main and auxiliary storage units, respectively. In general, the main and auxiliary storage units will, if the erasing signal 1 is left out of consideration, have the following switching functions:

$$(t_1 \& H_{n-1} \& \bar{H}_n) v(A_n \& \bar{H}_n \& t_1) = A_n \quad (5)$$

$$(t_2 \& A_n) v(H_n \& H_{n-1}) = H_n \quad (6)$$

$n=1, 2, 3 \dots$

It will be seen from the pulse diagram of FIGURES 2 and 2a, that, while the output signal of the main storage unit of the nth counter stage (digital value 2^{n-1}) is equal to L, the number of times which the output signal of the corresponding auxiliary storage unit changes its condition will be an odd number, and more particularly, will be equal to at least 2^{n-1} ($n=0, 1, 2 \dots$). In order that, upon the appearance of an erasing signal ($1=L$), all of the outputs $A=0$ and all of the outputs $H=0$, the indicated switching functions can be modified as follows:

$$(t_1 \& \bar{H}_0 \& \bar{1}) v(A_0 \& \bar{1} \& \bar{H}_0 \& t_1) = A_0 \quad (7)$$

$$(t_2 \& A_0) v(H_0 \& \bar{1} \& \bar{A}_0 \& t_2) = H_0 \quad (8)$$

$$(t_1 \& H_{n-1} \& \bar{H}_n) v(A_n \& \bar{1} \& \bar{H}_n \& t_1) = A_n \quad (9)$$

$$(t_2 \& A_n) v(H_n \& H_{n-1}) = H_n \quad (10)$$

$n=1, 2, 3 \dots$

The count should, upon the appearance of counting signal t_1 , change only if the counter is cleared for counting. This requirement can be met by introducing a counting command z or a special clear for counting signal z_2 into the counter stage of the lowest order binary digit. Advantageously, the clear for counting signal z_2 is so synchronized as to appear at the start of an auxiliary counting signal t_2 .

A counting command z can be given at any instant. If the clear for counting command z_2 is to be introduced, there is formed from z , with the help of a storage unit, a signal z_1 ; this storage unit for the signal z_1 is set with the first counting signal t_1 when $z=L$ and $1=0$, and is reset (erased) with $1=L$ or with the first counting signal t_1 which appears after z is again equal to 0. The switching function for z_1 is thus:

$$(z \& t_1 \& \bar{1}) v(z_1 \& \bar{1} \& \bar{z} \& t_1) = z_1 \quad (11)$$

or transposed

$$(z \& t_1 \& \bar{1}) v(z_1 \& z \& \bar{1}) v(z_1 \& \bar{t}_1 \& \bar{1}) = z_1 \quad (12)$$

The start and finish of z_1 is indeterminable throughout a duration during which $t_1=L$, because z can become either L or 0 while t_1 is already equal to L.

The desired signal z_2 can be obtained with the help of z_1 by means of a further storage unit. This further storage unit is set with the first auxiliary counting signal t_2 after $z_1=L$, and is erased with $1=L$ or with the first auxiliary counting signal t_2 after z_2 is again equal to 0. The switching function for z_2 is thus

$$(z_1 \& t_2) v(z_2 \& \bar{1} \& \bar{z}_1 \& t_2) = z_2 \quad (13)$$

or transposed

$$(z_1 \& t_2) v(z_2 \& z_1) v(z_2 \& \bar{t}_2 \& \bar{1}) = z_2 \quad (14)$$

Inasmuch as there are time intervals between the signals t_1 , t_2 , the thus-formed signal z_2 begins and ends with the leading flank of a signal t_2 . The signals z , z_1 and z_2 are shown in the pulse diagram of FIGURE 13a.

FIGURE 3 shows a circuit for producing z_2 in accordance with the functions set forth in Equations 12 and 14. One of the storage units comprises input AND-circuits $\&_1$ to $\&_3$ which control an OR/NOT-circuit v_4 , whose output in turn is connected to a NOT-circuit 5. The other storage unit comprises input AND-circuits $\&_6$ to $\&_8$ which control an OR/NOT-circuit v_9 , whose output in turn is connected to a NOT-circuit 10.

The signal z_1 appears at the output of the NOT-circuit 5, the signal z_2 appears at the output of the NOT-circuit 10, and the signal z_2 appears at the output of the OR/NOT-circuit v_9 . The AND-circuit $\&_1$ is controlled by the signals t_1 , z and $\bar{1}$ and the output signal z_1 of its own storage unit, and the AND-circuit $\&_3$ is controlled by the signals $\bar{t}_1$, $\bar{1}$ and the output signal z_1 of its own storage unit. The AND-circuit $\&_8$ is controlled by the signals t_2 and z_1 , the AND-circuit $\&_7$ is controlled by the signal z_1 and by the output signal z_2 of its own storage unit, and the AND-circuit $\&_6$ is controlled by the signals $\bar{1}$, t_2 and the output signal z_2 of its own storage unit.

If the clear for counting signal z_2 is considered, the switching functions of A_0 and H_0 change. This is again shown in the pulse diagram of FIGURE 2a. The signal A_0 can change from 0 to L or from L to 0 only when $z_2=L$. This condition is met, for example, by replacing in the switching function (7) for A_0 the expression in the first bracket by $(t_1 \& \bar{H}_0 \& z_2)$, and by replacing the expression in the second bracket by $(A_0 \& \bar{1} \& \bar{H}_0 \& t_1 \& z_2)$. In order that A_1 as well changes its condition at the correct instants of time, the switching function for H_0 is also modified, namely, so that for the duration of the counting signals t_1 which occur within the time interval while $z_2=0$, H_0 is certain to be 0. This can be achieved by replacing the expression in the second bracket of Equation 8 for H_0 by $(H_0 \& z_2 \& \bar{A}_0 \& t_2)$. As a result of this, the above-mentioned change for the expression in the second bracket for A_0 becomes superfluous. There is thus obtained:

$$(t_1 \& z_2 \& H_0) v(A_0 \& \bar{1} \& H_0 \& t_1) = A_0 \quad (15)$$

$$(t_2 \& A_0) v(H_0 \& z_2 \& \bar{A}_0 \& t_2) = H_0 \quad (16)$$

The functions according to Equations 9 and 10 apply unchanged for the succeeding counter stages.

Many transpositions are possible for the given functions. For example, Equation 9 can be transposed into

$$(t_1 \& H_{n-1} \& \bar{H}_n) v[A_n \& \bar{1} \& (\bar{H}_n \& \bar{t}_1)] = A_n \quad (17)$$

$$(t_1 \& H_{n-1} \& \bar{H}_n) v(A_n \& \bar{H}_n \& \bar{1}) v(A_n \& \bar{t}_1 \& \bar{1}) = A_n \quad (18)$$

$$[(t_1 \& H_{n-1} \& \bar{H}_n) \& (\bar{H}_n \& \bar{t}_1)] v[(A_n \& \bar{1}) \& (\bar{H}_n \& \bar{t}_1)] = A_n \quad (19)$$

$$(\bar{H}_n \& \bar{t}_1) \& [(t_1 \& H_{n-1} \& \bar{H}_n) v(A_n \& \bar{1})] = A_n \quad (20)$$

$$\bar{H}_n \& \bar{t}_1 \& [(t_1 \& H_{n-1} \& \bar{H}_n) v(A_n \& \bar{1})] = A_n \quad (21)$$

$$(\bar{H}_n \& t_1) v(t_1 \& H_{n-1} \& \bar{H}_n) v(A_n \& \bar{1}) = A_n \quad (22)$$

$$H_n \& t_1 \& [(t_1 \& H_{n-1} \& \bar{H}_n) vA_n] \& 1 = A_n \quad (23)$$

$$(H_n \& t_1) v(t_1 \& H_{n-1} \& \bar{H}_n) vA_n v1 = A_n \quad (24)$$

$$t_1 \& H_{n-1} \& H_n \& A_n \bar{H}_n \& \bar{1} \& A_n \& \bar{t}_1 \& \bar{1} = A_n \quad (18a)$$

$$(\bar{t}_1 v \bar{H}_{n-1} v H_n) \& (\bar{A}_n v H_n v 1) \& (\bar{A}_n v t_1 v 1) = A_n \quad (18b)$$

$$\bar{t}_1 v \bar{H}_{n-1} v H_n v \bar{A}_n v H_n v 1 v \bar{A}_n v t_1 v 1 = A_n \quad (18c)$$

FIGURE 4a shows, for example, a circuit operating according to the function set forth in Equation 18, while FIGURE 4b shows a circuit operating according to Equation 22 and FIGURE 4c shows a circuit operating according to Equation 24.

The storage unit of FIGURE 4a comprises AND-circuits $\&_{11}$ to $\&_{13}$ which control an OR/NOT-circuit v_{14} , whose output is connected to a NOT-circuit 15.

The storage unit according to FIGURE 4b comprises AND-circuits $\&_{16}$ to $\&_{18}$. The AND-circuit $\&_{16}$ controls an OR/NOT-circuit v_{20} , while the AND-circuits $\&_{17}$, $\&_{18}$, control an OR/NOT-circuit v_{19} which likewise controls the OR/NOT-circuit v_{20} .

The storage unit according to FIGURE 4c comprises two input AND-circuits $\&_{141}$, $\&_{142}$ and two OR/NOT-circuits v_{143} , v_{144} . The AND-circuit $\&_{142}$ controls the OR/NOT-circuit v_{143} while the outputs of the AND-circuit $\&_{141}$ and the OR/NOT-circuit v_{143} control the OR/NOT-circuit v_{144} .

The functions (15) and (16) can be similarly transposed for A_0 and H_0 . For example, Equation 18 can be modified into analogous form

$$(t_1 \& z_2 \& \bar{H}_0) v(A_0 \& \bar{H}_0 \& \bar{1}) v(A_0 \& \bar{t}_1 \& \bar{1}) = A_0 \quad (25)$$

$$(t_2 \& A_0) v(H_0 \& z_2 \& A_0) v(H_0 \& z_2 \& \bar{t}_2) = H_0 \quad (26)$$

and the Equation 22 can be given an analogous form

$$(H_0 \& t_1) v(t_1 \& z_2 \& \bar{H}_0) v(A_0 \& \bar{1}) = A_0 \quad (27)$$

$$(A_0 \& t_2) v(t_2 \& A_0) v(H_0 \& z_2) = H_0 \quad (28)$$

FIGURE 5 shows the circuitry of the first four counter stages of a binary counter according to Equations 25, 26, 18, 10, it being possible, of course, to increase the number of counter stages to any desired extent.

The main storage units are referenced, depending on the digital value, as S_{A0} , S_{A1} , S_{A2} , S_{A3} , while the corresponding auxiliary storage units are referenced S_{H0} , S_{H1} , S_{H2} , S_{H3} . The main storage unit and the auxiliary storage unit of one binary digit form one counter stage. All of the main storage units are similarly constructed and are, in fact, as shown in FIGURE 4a. There are three controlled input stages for each of the main storage units, as shown at $\&_{26}$, $\&_{27a}$, $\&_{28}$, $\&_{36}$, $\&_{37a}$, $\&_{38}$, $\&_{46}$, $\&_{47a}$, $\&_{48}$, $\&_{56}$, $\&_{57a}$, $\&_{58}$, which control four respective OR/NOT-circuits v_{30} , v_{40} , v_{50} , v_{60} , whose outputs, in turn, are connected, respectively, to NOT-circuits 31, 41, 51, 61. The signals $\bar{A}$ appear at the outputs of the OR/NOT-circuits, while the signals A appear at the outputs of the NOT-circuits.

The result of the count can be taken off, for example, at the instants of the auxiliary counting signals t_2 , or at other suitable instants of time. This applies for all of the embodiments to be described below.

The AND-circuits $\&_{26}$, $\&_{36}$, $\&_{46}$, $\&_{56}$, are controlled by the negated erasing signal $\bar{1}$, the output signal $\bar{H}$ of the auxiliary storage unit of the same binary digit, and the output signal A of the own storage unit S_A . The AND-circuits $\&_{27a}$, $\&_{37a}$, $\&_{47a}$, $\&_{57a}$, are controlled by the negated counting signal $\bar{t}_1$, the negated erasing signal $\bar{1}$, and the output signal A of the own storage unit S_A . The AND-circuits $\&_{28}$, $\&_{38}$, $\&_{48}$, $\&_{58}$, are controlled by the counting signal t_1 and the output signal $\bar{H}$ of the corresponding auxiliary storage unit. The AND-circuit $\&_{26}$ of the lowest order binary digit is additionally controlled by the clear for counting signal z_2 , and the AND-circuits $\&_{38}$, $\&_{48}$, $\&_{58}$ of the higher order binary digits are additionally controlled by the output signal H of the auxiliary storage unit of the preceding binary digit.

In the counter of FIGURE 5, all of the auxiliary storage units, with the exception of the auxiliary storage unit S_{H0} , pertaining to the lowest order binary digit, are simi-

larly constructed. The auxiliary storage unit S_{H0} has three input AND-circuits $\&_{22}$, $\&_{23a}$, $\&_{23b}$, which control an OR/NOT-circuit v_{24a} whose output in turn is connected to a NOT-circuit 25. The succeeding auxiliary storage units S_{H1} to S_{H3} have, as input stages, AND-circuits $\&_{32}$, $\&_{33}$, $\&_{42}$, $\&_{43}$, $\&_{52}$, $\&_{53}$, which control OR/NOT-circuits v_{34} , v_{44} , v_{54} , respectively, the outputs of which are connected, respectively, to NOT-circuits 35, 45, 55. The signals H_0 , H_1 , H_2 , H_3 , appear at the outputs of the OR/NOT-circuits v_{24a} , v_{34a} , v_{44a} , v_{54a} , while the signals H_0 , H_1 , H_2 , H_3 , appear at the outputs of the NOT-circuits 25, 35, 45, 55. The AND-circuits $\&_{22}$, $\&_{32}$, $\&_{42}$, $\&_{52}$, are controlled by the auxiliary counting signal t_2 and the output signal A of main storage unit S_A of the same binary digit. The AND-circuit $\&_{23a}$ is controlled by the clear for counting signal z_2 , the negated auxiliary counting signal t_2 , and the output signal H_0 of the own auxiliary storage unit S_{H0} . The AND-circuit $\&_{23b}$ is controlled by the clear for counting signal z_2 , the output signal A_0 of the main storage unit S_{A0} of the same binary digit, and the output signal H_0 of the own auxiliary storage unit S_{H0} . The AND-circuits $\&_{33}$, $\&_{43}$, $\&_{53}$, are controlled by the output signal H of the own auxiliary storage unit S_H and the output signal H of the preceding auxiliary storage unit S_H .

The switching functions of the main and auxiliary storage units are summarized as follows:

$$(t_1 \& z_2 \& \bar{H}_0) v(A_0 \& \bar{H}_0 \& \bar{1}) v(A_0 \& \bar{t}_1 \& \bar{1}) = A_0 \quad (25)$$

$$(t_1 \& H_0 \& \bar{H}_1) v(A_1 \& \bar{H}_1 \& \bar{1}) v(A_1 \& \bar{t}_1 \& \bar{1}) = A_1 \quad \left. \begin{array}{l} \text{according} \\ \text{to (18)} \end{array} \right\}$$

$$(t_1 \& H_1 \& \bar{H}_2) v(A_2 \& \bar{H}_2 \& \bar{1}) v(A_2 \& \bar{t}_1 \& \bar{1}) = A_2 \quad (26)$$

$$(t_1 \& H_2 \& \bar{H}_3) v(A_3 \& \bar{H}_3 \& \bar{1}) v(A_3 \& \bar{t}_1 \& \bar{1}) = A_3 \quad (26)$$

$$(t_2 \& A_0) v(H_0 \& z_2 \& A_0) v(H_0 \& z_2 \& \bar{t}_2) = H_0 \quad \left. \begin{array}{l} \text{according} \\ \text{to (10)} \end{array} \right\}$$

$$(t_2 \& A_1) v(H_1 \& H_0) = H_1 \quad (29)$$

$$(t_2 \& A_2) v(H_2 \& H_1) = H_2 \quad (30)$$

If a larger number of counter stages are combined, it is expedient to extract $\bar{t}_1$ and $\bar{1}$ from the function for A and to form the same outside of the counter stages. There is thus obtained from (25) and (18)

$$(t_1 \& z_2 \& \bar{H}_0) v(A_0 \& \bar{H}_0 \& \bar{1}) v(A_0 \& \bar{t}_1') = A_0 \quad (29)$$

$$(t_1 \& H_{n-1} \& \bar{H}_n) v(A_n \& \bar{H}_n \& \bar{1}) v(A_n \& \bar{t}_1') = A_n \quad (30)$$

$n=1, 2, 3 \dots$

where

$$\bar{t}_1 \& \bar{1} = \bar{t}_1' \quad (31)$$

The circuitry of one counter stage can, for example, be combined into one modular unit. The switching function for H_0 can be so transposed that the counter can be constituted by similar modular units. There is obtained from (26)

$$(t_2 \& A_0) v(H_0 \& e) = H_0 \quad (32)$$

where

$$(z_2 \& A_0) v(z_2 \& \bar{t}_2) = e \quad (33)$$

Equation 33 can be transposed to yield

$$\bar{z}_2 v(\bar{A}_0 \& \bar{t}_2) = e \quad (34)$$

FIGURE 6 shows a further embodiment for the first four counter stages according to (29), (30), (32), (10). Those components of FIGURE 6 which correspond to the components of FIGURE 5 are identified by the same reference numerals. It will be seen that, in the counter of FIGURE 6, all of the main storage units are similar to each other and all of the auxiliary counter units are similar to each other.

The main storage units S_{A0} to S_{A3} of FIGURE 6 correspond to the main storage units of the counter of FIGURE 5, except for the AND-circuits $\&_{27}$, $\&_{37}$, $\&_{47}$, $\&_{57}$ which, in FIGURE 6, take the place of AND-circuits $\&_{27a}$, $\&_{37a}$, $\&_{47a}$, $\&_{57a}$ of FIGURE 5. The AND-circuits $\&_{27}$, $\&_{37}$,

$\&_{47}$, $\&_{57}$, are controlled by the signal $\bar{t}_1'$ and the output signals A of their own storage units.

The auxiliary storage units S_{H1} to S_{H3} of FIGURE 6 corresponds to the auxiliary storage units of the counter of FIGURE 5. As for the auxiliary storage unit S_{H0} of the lowest order binary digit, the AND-circuits $\&_{23a}$ and $\&_{23b}$ of FIGURE 5 are replaced by the AND-circuit $\&_{23}$, and an OR/NOT-circuit v_{24} having but two inputs replaces the OR/NOT-circuit v_{24a} of the auxiliary storage unit S_{H0} of FIGURE 5. The input AND-circuit $\&_{22}$ of the auxiliary storage unit S_{H0} of the counter of FIGURE 6 is, as in the counter of FIGURE 5, controlled by the output signal A_0 of the main storage unit S_{A0} of the same binary digit and the auxiliary signal t_2 . The input AND-circuit $\&_{23}$ is controlled by the signal e and the output signal H_0 of the own storage unit. The AND-circuits $\&_{22}$ and $\&_{23}$ control the OR/NOT-circuit v_{24} which puts out the signal $\bar{H}_0$. The output of OR/NOT-circuit v_{24} is connected to a NOT-circuit 25, at whose output appears the signal H_0 .

The switching functions for the main and auxiliary storage units according to FIGURE 6 are as follows:

$$(t_1 \& z_2 \& \bar{H}_0) v(A_0 \& \bar{H}_0 \& \bar{1}) v(A_0 \& \bar{t}_1') = A_0 \quad (29)$$

$$\left. \begin{aligned} (t_1 \& H_0 \& \bar{H}_1) v(A_1 \& \bar{H}_1 \& \bar{1}) v(A_1 \& \bar{t}_1') = A_1 \\ (t_1 \& H_1 \& \bar{H}_2) v(A_2 \& \bar{H}_2 \& \bar{1}) v(A_2 \& \bar{t}_1') = A_2 \\ (t_1 \& H_2 \& \bar{H}_3) v(A_3 \& \bar{H}_3 \& \bar{1}) v(A_3 \& \bar{t}_1') = A_3 \end{aligned} \right\} \text{according to (30)}$$

$$(t_2 \& A_0) v(H_0 \& e) = H_0 \quad (32)$$

$$\left. \begin{aligned} (t_2 \& A_1) v(H_1 \& H_0) = H_1 \\ (t_2 \& A_2) v(H_2 \& H_1) = H_2 \\ (t_2 \& A_3) v(H_3 \& H_2) = H_3 \end{aligned} \right\} \text{according to (10)}$$

Here, $\bar{t}_1'$ can be formed according to (31), and e according to (34), and FIGURES 7 and 8 show circuit arrangements forming these signals. The arrangement for forming $\bar{t}_1'$ comprises an AND/NOT-circuit $\&_{70}$ which is controlled by the negated counting signal $\bar{t}_1$ and the negated erasing signal $\bar{1}$, the output of which AND/NOT-circuit $\&_{70}$ is connected to an amplifying NOT-circuit 71 which puts out the signal $\bar{t}_1'$. The arrangement for forming the signal e comprises two AND-circuits $\&_{72}$, $\&_{73}$, which control an OR/NOT-circuit v_{74} that puts out the signal e . The AND-circuit $\&_{72}$ is controlled by the negated clear for counting signal $\bar{z}_2$, and the AND-circuit $\&_{73}$ is controlled by the auxiliary counting signal t_2 and the output signal $\bar{A}_0$ of the main storage unit of the lowest order binary digit. The two circuit arrangements shown in FIGURES 7 and 8 are connected to the counter of FIGURE 6 as auxiliary attachments.

As set forth above, the counter stages can be modified in various ways. FIGURE 9, for example, shows a counter having four counter stages in which the first stage is divided into a part which corresponds to the succeeding counter stages and a further, supplemental part according to FIGURE 8, and in which the main storage units S_{A0} to S_{A3} are arranged to carry out the switching functions (27) and (22), the circuitry being as in FIGURE 4b. The auxiliary storage units S_{H0} to S_{H3} are shown in FIGURE 6 and are controlled in the same way. The main storage units S_{A0} and S_{A3} of the counter of FIGURE 9 are, as set forth above, as shown in FIGURE 4b. Each of the main storage units S_{A0} to S_{A3} comprises three AND-circuits $\&_{16}$ to $\&_{18}$. The AND-circuits $\&_{17}$ and $\&_{18}$ control a corresponding OR/NOT-circuit v_{19} . The OR/NOT-circuits v_{19} as well as the AND-circuits $\&_{16}$ control corresponding OR/NOT-circuits v_{20} . The signals A_0 to A_3 appear at the outputs of the corresponding OR/NOT-circuits v_{20} , while the signals a_0 to a_3 appear at the outputs of the corresponding OR/NOT-circuits v_{19} . The AND-circuits $\&_{16}$ are controlled by the counting signal t_1 as well as by the output signal H of the auxiliary storage unit of the same binary digit. All of the AND-circuits $\&_{17}$ are controlled by the counting signal t_1 and the negated output signal $\bar{H}$ of the auxiliary storage unit of the same binary digit.

The input AND-circuit $\&_{17}$ of the lowest order binary digit is additionally controlled by the clear for counting signal z_2 , and the input AND-circuits $\&_{17}$ of the main storage units of the succeeding higher order binary digits 5 are controlled by the negated erasing signal $\bar{1}$ and the unit of the preceding binary digit. The AND-circuits $\&_{18}$ are controlled by the negated erasing signal 1 and the output signal A of the own main storage unit S_A .

As will be explained below in conjunction with FIGURE 4b, $a_n = \bar{A}_n$. When the signal appearing at the output a_n of the OR/NOT-circuit v_{19} is equal to L, the signal at output A_n will be equal to 0 because a_n is applied to one of the inputs of the OR/NOT-circuit v_{20} . When the signal at output $a_n = 0$, the signal L must appear at the output of the AND-circuit $\&_{17}$ or at the output of the AND-circuit $\&_{18}$. But the signal at the output of AND-circuit $\&_{18}$ can be L only when both inputs of this AND-circuit are L, i.e., when $A_n = L$; if the signal at the output of AND-circuit $\&_{17} = L$, the signal $\bar{H}_n$ must also be equal to L, but in that case the input signal H_n of AND-circuit $\&_{16} = 0$. Hence, the output signal of AND-circuit $\&_{16}$ is also equal to 0, thus both inputs of the OR/NOT-circuit $v_{20} = 0$, and, therefore, the signal at the output A_n is in this case equal to L.

FIGURE 10 shows a further example of a counter having four counter stages, in which the main storage units are arranged as shown in FIGURE 4c and the auxiliary storage units correspond, in arrangement and control, with the auxiliary storage units as shown in FIGURE 9. All 30 of the counter stages are similarly constructed. The main and auxiliary storage units each have as input stages two AND-circuits.

FIGURE 11 is a pulse diagram for a binary counter in which, while the output signal of a main storage unit is L, the output of the corresponding auxiliary storage unit will change its condition only once. The reference numerals are selected in the same manner as in the pulse diagram of FIGURE 2a. For the purposes of simplicity, the signals 1 and z_2 are, in the instant case, left out of consideration.

FIGURE 12 shows a non-presettable binary counter according to the pulse diagram of FIGURE 11. The main storage units are arranged as shown in FIGURE 4c. Due to the difference in control, the reference numerals include the letter a . The auxiliary storage units comprise three input AND-circuits $\&_{151}$, $\&_{152}$, $\&_{153}$; $\&_{161}$, $\&_{162}$, $\&_{163}$; $\&_{171}$, $\&_{172}$, $\&_{173}$; $\&_{181}$, $\&_{182}$, $\&_{183}$, which control OR/NOT-circuits v_{154} , v_{164} , v_{174} , v_{184} , respectively, the outputs of which are connected to NOT-circuits 155, 50 165, 175, 185, respectively. The switching function for this binary counter is as follows:

$$(H_0 \& t_1) v(t_1 \& z_2 \& \bar{H}_0) vA_0 v1 = A_0$$

$$(H_1 \& \bar{A}_0) v(\bar{A}_0 \& H_0 \& \bar{H}_1) vA_1 v1 = A_1$$

$$(H_2 \& \bar{A}_1) v(\bar{A}_1 \& H_1 \& \bar{H}_2) vA_2 v1 = A_2$$

$$(H_3 \& \bar{A}_2) v(\bar{A}_2 \& H_2 \& \bar{H}_3) vA_3 v1 = A_3$$

$$(t_2 \& A_0) v(H_0 \& z_2 \& A_0) v(H_0 \& z_2 \& \bar{t}_2) = H_0$$

$$(t_2 \& A_0 \& A_1) v(H_1 \& \bar{A}_0 \& \bar{1}) v(H_1 \& H_0) = H_1$$

$$(t_2 \& H_1 \& A_1 \& A_2) v(H_2 \& \bar{A}_1 \& \bar{1}) v(H_2 \& H_1) = H_2$$

$$(t_2 \& H_2 \& A_2 \& A_3) v(H_3 \& \bar{A}_2 \& \bar{1}) v(H_3 \& H_2) = H_3$$

Presetting the binary counter

In many cases it is desirable to preset the binary counter to a certain binary number. Before the counter is preset to this number, the previous count should be erased. The presetting signals k should be taken over by the main storage units of the counter stages before the count is carried out. Upon the appearance of the first signal t_1 to be counted, the counter is to count from the preset

number onward. In practice, the arrangement should be such that, beginning with the instant at which the counter is ready to carry out its counting operation (i.e., when z_2 , the clear for counting signal, is equal to L), the presetting signals k have no influence on the counter. Moreover, while a counting operation is in progress, the presetting of a new number can be made ready. The presetting signals which are then present should be taken over by the main storage units of the counter stages only after the occurrence of a new erasing signal $1=L$.

According to the present invention, means are provided to facilitate the presetting while maintaining the above-described switching functions. The presetting of the counter will be explained, with reference being had to the pulse diagram of FIGURE 13a, in conjunction with the arrangements shown in FIGURES 14a, 14b, and 15.

The pulse diagram of FIGURE 13a shows a presetting signal k_0 for the binary digit having the digit value 2^0 , a presetting signal k_1 for the binary digit having the value 2^1 , and so on. The presetting signals can be adjusted, for example, by means of switches (not illustrated), or by means of storage units or other electronic components. These presetting signals k can be applied to the main storage units of the counter stages in the form of additional input signals.

According to a further feature of the present invention, the presetting signals k are combined with a clear for presetting signal f , which appears after erasing ($1=L$) and disappears with the appearance of a clear for counting signal ($z_2=L$), it being possible for a new signal f to appear only after a further erasing ($1=L$).

Also shown is an auxiliary signal m needed for producing the signal f . The other signals correspond to the similarly identified signals of the pulse diagram of FIGURE 2a, and have been explained above.

In order to produce the clear for presetting signal f , the signal m is first formed in a storage unit. This signal m is stored upon the appearance of an erasing signal $1=L$ and is itself erased upon the appearance of the dominating clear for counting signal $z_2=L$. This is represented by

$$(1vm) \& \bar{z}_2 = m \quad (35)$$

or, since z_2 can become equal to L only after 1 has become equal to 0, by

$$1v(m \& \bar{z}_2) = m \quad (36)$$

The clear for presetting signal f is derived from m and 1 in accordance with the following function:

$$(m \& 1) = f \quad (37)$$

or transposed

$$\bar{m}v = f \quad (38)$$

FIGURE 14a shows a circuit for forming the clear for presetting signal f according to Equations 36 and 38. The circuit comprises a storage unit S_f and OR/NOT-circuit v_{78} at whose output the signal f appears. The storage unit S_f comprises an AND-circuit $\&_{74}$ which is controlled by the negated clear for counting signal $\bar{z}_2$ and the output signal m of the own storage unit, and OR/NOT-circuit v_{76} which is controlled by AND-circuit $\&_{75}$ and the erasing signal 1, and NOT-circuit 77 which is connected to the output of the OR/NOT-circuit v_{76} and which put out the signal m . The OR/NOT-circuit v_{78} is controlled by the OR/NOT-circuit v_{76} and the erasing signal 1. If, as is the case, for example, with the counters of FIGURES 5 and 6, all of the inputs are applied to AND-circuits, the clear for presetting signal f can be formed by means of an arrangement according to FIGURE 14b. Here, the storage unit comprises two AND-circuits $\&_{80}$, $\&_{81}$, which control an OR/NOT-circuit v_{82} , whose output, in turn, is connected to a NOT-circuit 83. The AND-circuit $\&_{80}$ is controlled by the negated clear for counting signal $\bar{z}_2$ and the output signal

m of the own storage unit, and the AND-circuit $\&_{81}$ is controlled by the erasing signal 1. A further AND/NOT-circuit $\&_{84}$ is controlled by the NOT-circuit 83 and the negated erasing signal $\bar{1}$. The output of AND/NOT-circuit $\&_{84}$ is connected to a NOT-circuit 85 from whose output the signal f is taken.

The counter stages according to FIGURES 5, 6, 9, 10 and 12 can be modified so that they can take over the presetting signals k , so long as $f=L$. This can be achieved by adding to the main storage units of the counter stages a further term

$$v(k_n \& f) \quad (39)$$

$$n=0, 1, 2, 3$$

In the arrangements of FIGURES 5 and 6, there is applied to the counter stage for the $(n+1)^{th}$ binary digit having the value 2^n , the output of the AND-circuit $(k_n \& f)$, as an additional input to the corresponding OR/NOT-circuits v_{30} , v_{40} , v_{50} , v_{60} of the main storage unit S_A ; in the embodiments of FIGURES 9, 10 and 12, this output is applied to the respective OR/NOT-circuits v_{19} , v_{143} , v_{143a} , of the output storage unit S_A .

The switching function for A_0 and A_n then becomes, according to (29) and (30) which were used for obtaining the counter of FIGURE 6:

$$(t_2 \& z_2 \& \bar{H}_0) v(A_0 \& \bar{H}_0 \& \bar{1}) v(A_0 \& \bar{t}_1') v(k_0 \& f) = A_0 \quad (40)$$

$$(t_1 \& H_{n-1} \& \bar{H}_n) v(A_n \& \bar{H}_n \& \bar{1}) v(A_n \& \bar{t}_1') v(k_n \& f) = A_n \quad (41) \\ n=1, 2, 3 \dots$$

FIGURE 15 shows a presettable binary counter based on the counter of FIGURE 6, there being illustrated the four first counter stages operating according to Equations 40, 41, 32, 10. More stages may be provided. The counter of FIGURE 15 differs from that of FIGURE 6 only in that additional AND-circuits $\&_{29}$, $\&_{39}$, $\&_{49}$, $\&_{59}$, are provided which are controlled by a respective presetting signal k_0 , k_1 , k_2 , k_3 , with these four of these AND-circuits being also controlled by the clear for presetting signal f . The outputs of the AND-circuits $\&_{29}$, $\&_{39}$, $\&_{49}$, $\&_{59}$, are applied to respective OR/NOT-circuits v_{30a} , v_{40a} , v_{50a} , v_{60a} , which have one more input than the OR/NOT-circuits v_{30} , v_{40} , v_{50} , v_{60} , of FIGURE 6. The switching functions for the main and auxiliary storage units are as follows:

$$(t_1 \& z_2 \& \bar{H}_0) v(A_0 \& \bar{H}_0 \& \bar{1}) v(A_0 \& \bar{t}_1') v(k_0 \& f) = A_0 \quad (40)$$

$$(t_1 \& H_0 \& \bar{H}_1) v(A_1 \& \bar{H}_1 \& \bar{1}) v(A_1 \& \bar{t}_1') v(k_1 \& f) = A_1 \quad (41)$$

$$(t_1 \& H_1 \& \bar{H}_2) v(A_2 \& \bar{H}_2 \& \bar{1}) v(A_2 \& \bar{t}_1') v(k_2 \& f) = A_2 \quad (42)$$

$$(t_1 \& H_2 \& \bar{H}_3) v(A_3 \& \bar{H}_3 \& \bar{1}) v(A_3 \& \bar{t}_1') v(k_3 \& f) = A_3 \quad (43)$$

$$(A_0 \& t_2) v(H_0 \& e) = H_0 \quad (32)$$

$$(A_1 \& t_2) v(H_1 \& H_0) = H_1 \quad (33) \quad \left. \begin{array}{l} (A_2 \& t_2) v(H_2 \& H_1) = H_2 \\ (A_3 \& t_2) v(H_3 \& H_2) = H_3 \end{array} \right\} \text{according to (10)}$$

$$(A_2 \& t_2) v(H_2 \& H_1) = H_2 \quad (34) \quad \left. \begin{array}{l} (A_3 \& t_2) v(H_3 \& H_2) = H_3 \\ (A_0 \& t_2) v(H_0 \& e) = H_0 \end{array} \right\} \text{according to (10)}$$

$$(A_3 \& t_2) v(H_3 \& H_2) = H_3 \quad (35)$$

Again, the signals z_2 , $\bar{t}_1'$, e , can be produced by means of the arrangements shown in FIGURES 3, 7 and 8.

Inasmuch as the presetting signals k are stored by the main storage units S_A of the counter, it is sufficient if the k signals are of short duration while $f=L$.

Explanation of the function of a static counter

The function of static counters will be explained with reference to the timed sequence of the circuit conditions of the presettable binary counter of FIGURE 15, in conjunction with FIGURES 3, 7, 8 and 14b (used, respectively for producing the signals z_2 , $\bar{t}_1'$, e and f), and the pulse diagram of FIGURE 16, the latter being a section taken from the pulse diagram of FIGURE 13a.

Steps 1 to 23 refer to the formation of the signals z_1 , z_2 , m and f by means of the arrangements shown in FIGURES 3 and 14b. Steps 24 to 135 show the instant-

taneous circuit condition of the main and auxiliary storage units S_A , S_H , according to FIGURE 15.

The signals t_1 which are to be counted, the auxiliary counting signals t_2 , the erasing signal 1, the counting command signal z , and the presetting signals k appear as shown in the pulse diagram of FIGURE 16. In the derivation of a circuit condition (step n) knowledge can be presumed, in addition to the given signals, only of those portions of the other signals shown in the diagram which have already been considered (steps 1, 2 . . . $n-1$). In order to make the circuit condition clear, the diagram shows the portions of the signals both for the condition 0 to be symbolized as well as for the condition L, with staggered height. For the sake of simplicity, the outputs of the AND-circuits are hereinafter referenced only with & and the subscript pertaining thereto.

Signal z_1

(1) So long as $1=L$, $\&_1$ is=0, $\&_2$ is=0, and $\&_3$ is=0 and therefore $z_1=0$.

(2) Due to the return of $z_1=0$ to $\&_2$ and $\&_3$, $\&_2$ is=0, $\&_3$ is=0, and so long as $z=0$, $\&_1$ is=0 and therefore $z_1=0$.

(3) Due to the return of $z_1=0$, $\&_2$ is=0, $\&_3$ is=0, and if $t_1=0$, $\&_1$ is also=0 and therefore $z_1=0$.

(4) Because $1=0$, $z=L$, and $t_1=L$, $\&_1$ is=L and therefore $z_1=L$.

(5) Due to the return of $z_1=L$ and so long as $z=L$ and $1=0$, $\&_2$ is=L and therefore $z_1=L$.

(6) Due to the return of $z_1=L$ and $1=0$ and $t_1=0$, $\&_3$ is=L and therefore $z_1=L$.

(7) Because $z=0$, $\&_1$ is=0, $\&_2$ is=0 and because $t_1=L$, $\&_3$ is=0 and therefore $z_1=0$.

(8) Due to the return of $z_1=0$, $\&_2$ is=0, $\&_3$ is=0 and because $z=0$, $\&_1$ is=0 and therefore $z_1=0$.

Signal z_2

(9) Because $z_1=0$, $\&_6$ is=0, $\&_7$ is=0 and when $1=L$, $\&_8$ is=0, and therefore $z_2=0$.

(10) Because $z_1=0$, $\&_6$ is=0 and due to the return of $z_2=0$, $\&_8$ is=0 and therefore $z_2=0$.

(11) Due to the return of $z_2=0$, $\&_7$ is=0, $\&_8$ is=0; if $t_2=0$, $\&_6$ is also=0 and therefore $z_2=0$.

(12) Because $z_1=L$ and $t_2=L$, $\&_6$ is=L and therefore $z_2=L$.

(13) Due to the return of $z_2=L$ and $z_1=L$, $\&_7$ is=L and therefore $z_2=L$.

(14) Due to the return of $z_2=L$ and $1=0$ and $t_2=0$, $\&_8$ is=L and therefore $z_2=L$.

(15) Because $z_1=0$, $\&_6$ is=0, $\&_7$ is=0, and when $t_2=L$, $\&_8$ is=0 and therefore $z_2=0$.

(16) Due to the return of $z_2=0$, $\&_7$ is=0, $\&_8$ is=0, and so long as $z_1=0$, $\&_6$ is=0 and therefore $z_2=0$.

Signal m

(17) So long as $1=L$, $\&_{81}$ is=L and therefore $m=L$.

(18) Due to the return of $m=L$ and $z_2=0$, $\&_{80}$ is=L and therefore $m=L$.

(19) Because $1=0$, $\&_{81}$ is=0 and because $z_2=L$, $\&_{80}$ is=0, and therefore $m=0$.

(20) Due to the return of $m=0$, $\&_{80}$ is=0 and because $1=0$, $\&_{81}$ is=0 and therefore $m=0$.

Signal f

(21) Because $1=L$, $\&_{84}$ is=L and therefore $f=0$.

(22) Because $1=0$ and $m=L$, $\&_{84}$ is=0 and therefore $f=L$.

(23) Because $m=0$, $\&_{84}$ is=L and therefore $f=0$.

Signals A_0 to A_3 as well as H_0 to H_3

(24) Because $1=L$, $\&_{26}$ is=0 and $\&_{70}$ is=L, when $\&_{70}=L$ $\bar{t}_1'$ is=0 and consequently $\&_{27}$ is=0, when $z_2=0$, $\&_{28}$ is=0, when $f=0$, $\&_{29}$ is=0 and therefore $A_0=0$.

(25) Because $k_0=L$ and $f=L$, $\&_{29}$ is=L and therefore $A_0=L$.

(26) Because $1=0$ and $t_1=0$, $\&_{70}$ is=0 and consequently $\bar{t}_1'=L$, since additionally $A_0=L$ is returned to $\&_{27}$, $\&_{27}$ is=L and therefore $A_0=L$.

(27) Because $A_0=0$, $\&_{22}$ is=0, when $z_2=0$, $\&_{72}$ is additionally=L and consequently $e=0$, when $e=0$, $\&_{23}$ is=0, and therefore $H_0=0$.

(28) Because $A_0=L$ and $t_2=L$, $\&_{22}$ is=L therefore $H_0=L$.

(29) Because $t_2=0$, $\&_{22}$ is=0 and when $z_2=0$, e is=0 (see 27), consequently $\&_{23}$ is=0 and therefore $H_0=0$.

(30) Conditions as in (28) and therefore $H_0=L$.

(31) Conditions as in (29) and therefore $H_0=0$.

(32) Conditions as in (28) and therefore $H_0=L$.

(33) Conditions as in (29) and therefore $H_0=0$.

(34) Conditions as in (28) and therefore $H_0=L$.

(35) Because $z_2=L$, $\&_{72}$ is=0 and because $A_0=L$, $\&_{73}$ is=0, thus $e=L$, because $e=L$ and the return of $H_0=L$, $\&_{23}$ is=L and therefore $H_0=L$.

(36) Because $z_2=L$, $\&_{72}$ is=0 and because $t_2=0$, $\&_{73}$ is=0, thus $e=L$, because $e=L$ and the return of $H_0=L$, $\&_{23}$ is=L and therefore $H_0=L$.

(37) Because $1=L$, $\&_{36}$ is=0, and $\&_{70}$ is=L, consequently $\bar{t}_1$ is=0 and also $\&_{37}$ is=0, because $H_0=0$, $\&_{38}$ is=0, and when $k_1=0$, $\&_{39}$ is=0 and therefore $A_1=0$.

(38) Due to the return of $A_1=0$, $\&_{36}$ is=0 and $\&_{37}$ is=0, when $k_1=0$, $\&_{39}$ is=0, because $t_1=0$, $\&_{38}$ is=0 and therefore $A_1=0$.

(39) Due to the return of $A_1=0$, $\&_{36}$ is=0 and $\&_{37}$ is=0, when $k_1=0$, $\&_{39}$ is=0, because $H_0=0$, $\&_{38}$ is=0 and therefore $A_1=0$.

(40) Conditions as in (38) and therefore $A_1=0$.

(41) Conditions as in (39) and therefore $A_1=0$.

(42) Conditions as in (38) and therefore $A_1=0$.

(43) Conditions as in (39) and therefore $A_1=0$.

(44) Conditions as in (38) and therefore $A_1=0$.

(45) Because $A_1=0$, $\&_{32}$ is=0, because $H_0=0$, $\&_{33}$ is=0, and therefore $H_1=0$.

(46) Due to the return of $H_1=0$, $\&_{33}$ is=0 and when $A_1=0$, $\&_{32}$ is=0 and therefore $H_1=0$.

(47) Due to the return of $H_1=0$, $\&_{33}$ is=0 and when $t_2=0$, $\&_{32}$ is=0 and therefore $H_1=0$.

(48) Because $1=L$, $\&_{46}$ is=0 and $\&_{70}$ is=L and consequently $\bar{t}_1'=0$, thus also $\&_{47}$ is=0, because $H_1=0$, $\&_{48}$ is=0 and when $f=0$, $\&_{49}$ is=0 and therefore $A_2=0$.

(49) Because $f=L$ and $k_2=L$, $\&_{49}$ is=L and therefore $A_2=L$.

(50) Because $1=0$ and $t_1=0$, $\&_{70}$ is=0 and consequently $\bar{t}_1'=L$; when $\bar{t}_1'=L$ and return of $A_2=L$, $\&_{47}$ is=L and therefore $A_2=L$.

(51) Because $A_2=0$, $\&_{42}$ is=0, because $H_1=0$, $\&_{43}$ is=0 and therefore $H_2=0$.

(52) Because $A_2=L$ and $t_2=L$, $\&_{42}$ is=L therefore $H_2=L$.

(53) Because $t_2=0$, $\&_{42}$ is=0 and because $H_1=0$, $\&_{44}$ is=0 and therefore $H_2=0$.

(54) Conditions as in (52) and therefore $H_2=L$.

(55) Conditions as in (53) and therefore $H_2=0$.

(56) Conditions as in (52) and therefore $H_2=L$.

(57) Conditions as in (53) and therefore $H_2=0$.

(58) Conditions as in (52) and therefore $H_2=L$.

(59) Conditions as in (53) and therefore $H_2=0$.

(60) Because $1=L$, $\&_{56}$ is=0 and $\&_{70}$ is=L and consequently $\bar{t}_1'=0$, thus also $\&_{57}$ is=0, because $H_2=0$, $\&_{58}$ is=0 and when $k_3=0$, $\&_{59}$ is=0 and therefore $A_3=0$.

(61) Due to the return of $A_3=0$, $\&_{56}$ is=0 and $\&_{57}$ is=0; because $t_1=0$, $\&_{58}$ is=0, because $k_3=0$, $\&_{59}$ is=0 and therefore $A_3=0$.

(62) Due to the return of $A_3=0$, $\&_{56}$ is=0, $\&_{57}$ is=0, because $H_2=0$, $\&_{58}$ is=0, because $k_3=0$, $\&_{59}$ is=0 and therefore $A_3=0$.

(63) Because $k_3=L$ and $f=L$, $\&_{59}$ is=L and therefore $A_3=L$.

(64) Because $1=0$ and $t_1=0$, $\&_{70}$ is=0 and consequently $\bar{t}_1'=L$, when $\bar{t}_1'=L$ and the return of $A_3=L$, $\&_{57}$ is=L and therefore $A_3=L$.

(65) Because $A_3=0$, $\&_{52}$ is=0 and because $H_2=0$, $\&_{53}$ is=0 and therefore $H_3=0$.

(66) Due to the return of $H_3=0$, $\&_{53}$ is=0 because $A_3=0$, $\&_{52}$ is=0 and therefore $H_3=0$.

(67) Due to the return of $H_3=0$, $\&_{53}$ is=0 and because $t_2=0$, $\&_{52}$ is=0 and therefore $H_3=0$.

(68) Because $A_3=L$ and $t_2=L$, $\&_{52}$ is=L and therefore $H_3=L$.

(69) Because $t_2=0$, $\&_{52}$ is=0 and because $H_2=0$, $\&_{53}$ is=0 and therefore $H_3=0$.

(70) Because $H_3=0$ and $1=0$ and the return $A_3=L$, $\&_{56}$ is=L and therefore $A_3=L$.

(71) Conditions as in (64) and therefore $A_3=L$.

(72) Conditions as in (68) and therefore $H_3=L$.

(73) Conditions as in (69) and therefore $H_3=0$.

(74) Conditions as in (70) and therefore $A_3=L$.

(75) Conditions as in (64) and therefore $A_3=L$.

(76) Conditions as in (68) and therefore $H_3=L$.

(77) Conditions as in (69) and therefore $H_3=0$.

The operation so far shows that the number 13 (LL0L) given by the presetting signals k has been stored into the main storage units S_A of the counter stages of FIGURE 15, the signals A_0, A_1, A_2, A_3 , having been derived to the steps 26, 44, 50, 75. Beginning with the next counting signal t_1 —this being the first signal to be counted following the clear for counting signal ($z_2=L$)—the count given out by the main storage units S_A is to increase by one.

(78) Because $f=0$, $\&_{29}$ is=0, because $H_0=L$, $\&_{28}$ is=0 and $\&_{28}$ is=0, when $t_1=L$, $\&_{70}$ is=L and consequently $\bar{t}_1$ is=0, thus also $\&_{27}$ is=0 and therefore $A_0=0$.

(79) Because $f=0$, $\&_{29}$ is=0, due to the return of $A_0=0$, $\&_{28}$ is=0 and $\&_{27}$ is=0, because $H_0=L$, $\&_{28}$ is=0 and therefore $A_0=0$.

(80) Because $f=0$, $\&_{29}$ is=0, due to the return of $A_0=0$, $\&_{28}$ is=0 and $\&_{27}$ is=0, because $t_1=0$, $\&_{28}$ is=0 and therefore $A_0=0$.

(81) Because $A_0=0$, $\&_{22}$ is=0 and when $t_2=L$ and $A_0=0$, $\&_{73}=L$, thus also $e=0$ and consequently $\&_{23}$ is=0 and therefore $H_0=0$.

(82) Due to the return of $H_0=0$, $\&_{23}$ is=0, because $A_0=0$, $\&_{22}$ is=0 and therefore $H_0=0$.

(83) Due to the return of $H_0=0$, $\&_{23}$ is=0, because $t_2=0$, $\&_{22}$ is=0 and therefore $H_0=0$.

(84) Because $t_1=L$ and $H_0=L$ and $H_1=0$, $\&_{38}$ is=L and therefore $A_1=L$.

(85) Due to the return of $A_1=L$ and $1=0$ and $H_1=0$, $\&_{36}$ is=L and therefore $A_1=L$.

(86) Because $t_1=0$ and $1=0$, $\&_{70}$ is=0, thus $\bar{t}_1=L$, when $\bar{t}_1=L$ and return of $A_1=L$, $\&_{37}$ is=L and therefore $A_1=L$.

(87) Because $A_1=L$ and $t_2=L$, $\&_{32}$ is=L and therefore $H_1=L$.

(88) Because $t_2=0$, $\&_{32}$ is=0, and because $H_0=0$, $\&_{33}$ is=0 and therefore $H_1=0$.

(89) Due to the return of $A_2=L$, $1=0$ and $H_2=0$, $\&_{46}$ is=L and therefore $A_2=L$.

(90) Conditions as in (50) and therefore $A_2=L$.

(91) Conditions as in (52) and therefore $H_2=L$.

(92) Conditions as in (53) and therefore $H_2=0$.

(93) Conditions as in (70) and therefore $A_3=L$.

(94) Conditions as in (64) and therefore $A_3=L$.

(95) Conditions as in (68) and therefore $H_3=L$.

(96) Conditions as in (69) and therefore $H_3=0$.

After this counting step, the main storage units S_A put out, as indeed they should, the number 14 (LLL0), signals A_0, A_1, A_2, A_3 , being derived as far as the steps 80, 86, 90, 94.

(97) Because $z_2=L$ and $t_1=L$ and $H_0=0$, $\&_{28}$ is=L and therefore $A_0=L$.

(98) Due to the return of $A_0=L$ and $1=0$ and $H_0=0$, $\&_{26}$ is=L and therefore $A_0=L$.

(99) Because $t_1=0$ and $1=0$, $\&_{70}$ is=0, thus $\bar{t}_1=L$, when $\bar{t}_1=L$ and return of $A_0=L$, $\&_{27}$ is=L and therefore $A_0=L$.

(100) Conditions as in (34) and therefore $H_0=L$.

(101) Conditions as in (35) and therefore $H_0=L$.

(102) Conditions as in (36) and therefore $H_0=L$.

(103) Conditions as in (85) and therefore $A_1=L$.

(104) Conditions as in (86) and therefore $A_1=L$.

(105) Conditions as in (87) and therefore $H_1=L$.

(106) Due to the return of $H_1=L$ and $H_0=L$, $\&_{33}$ is=L and therefore $H_1=L$.

(107) Conditions as in (89) and therefore $A_2=L$.

(108) Conditions as in (90) and therefore $A_2=L$.

(109) Conditions as in (52) and therefore $H_2=L$.

10 (110) Due to the return of $H_2=L$ and $H_1=L$, $\&_{43}$ is=L and therefore $H_2=L$.

(111) Conditions as in (70) and therefore $A_3=L$.

(112) Conditions as in (64) and therefore $A_3=L$.

(113) Conditions as in (68) and therefore $H_3=L$.

15 (114) Due to the return of $H_3=L$ and $H_2=L$, $\&_{53}$ is=L and therefore $H_3=L$.

After this counting step, the count has been increased to the number 15 (LLLL), signals A_0, A_1, A_2, A_3 , being derived as far as the steps 99, 104, 108, 112.

(115) Conditions as in (78) and therefore $A_0=0$.

(116) Conditions as in (79) and therefore $A_0=0$.

(117) Conditions as in (80) and therefore $A_0=0$.

(118) Conditions as in (81) and therefore $H_0=0$.

(119) Conditions as in (82) and therefore $H_0=0$.

(120) Conditions as in (83) and therefore $H_0=0$.

30 (121) Because $f=0$, $\&_{39}$ is=0, because $H_1=L$, $\&_{36}$ is=0, and $\&_{38}$ is=0, because $t_1=L$, $\&_{70}$ is=L, thus $\bar{t}_1=0$ and consequently $\&_{37}$ is=0 and therefore $A_1=0$.

(122) Because $f=0$, $\&_{39}$ is=0, due to the return of $A_1=0$, $\&_{36}$ is=0 and $\&_{37}$ is=0, and because $H_1=L$, $\&_{38}$ is=0 and therefore $A_1=0$.

(123) Because $f=0$, $\&_{39}$ is=0, due to the return of $A_1=0$, $\&_{36}$ is=0 and $\&_{37}$ is=0, and because $t_1=0$, $\&_{38}$ is=0, and therefore $A_1=0$.

(124) Because $A_1=0$, $\&_{32}$ is=0 and because $H_0=0$, $\&_{33}$ is=0, and therefore $H_1=0$.

(125) Due to the return of $H_1=0$, $\&_{33}$ is=0, because $t_2=0$, $\&_{32}$ is=0 and therefore $H_1=0$.

40 (126) Because $f=0$, $\&_{49}$ is=0, because $H_2=L$, $\&_{46}$ is=0 and $\&_{48}$ is=0, because $t_1=L$, $\&_{70}$ is=L, thus $\bar{t}_1=0$ and consequently $\&_{47}$ is=0 and therefore $A_2=0$.

(127) Because $f=0$, $\&_{49}$ is=0, due to the return of $A_2=0$, $\&_{46}$ is=0, and $\&_{47}$ is=0 and because $H_2=L$, $\&_{48}$ is=0, and therefore $A_2=0$.

(128) Because $f=0$, $\&_{49}$ is=0, due to the return of $A_2=0$, $\&_{46}$ is=0 and $\&_{47}$ is=0 and because $t_1=0$, $\&_{48}$ is=0, and therefore $A_2=0$.

45 (129) Because $A_2=0$, $\&_{42}$ is=0 and because $H_1=0$, $\&_{43}$ is=0, and therefore $H_2=0$.

(130) Due to the return of $H_2=0$, $\&_{43}$ is=0, because $t_2=0$, $\&_{42}$ is=0 and therefore $H_2=0$.

(131) Because $f=0$, $\&_{59}$ is=0, because $H_3=L$, $\&_{56}$ is=0 and $\&_{58}$ is=0, because $t_1=L$, $\&_{70}$ is=L, thus $\bar{t}_1=0$ and consequently $\&_{57}$ is=0 and therefore $A_3=0$.

(132) Because $f=0$, $\&_{59}$ is=0, due to the return of $A_3=0$, $\&_{56}$ is=0 and $\&_{57}$ is=0, and because $H_3=L$, $\&_{58}$ is=0 and therefore $A_3=0$.

50 (133) Because $f=0$, $\&_{59}$ is=0, due to the return of $A_3=0$, $\&_{56}$ is=0 and $\&_{57}$ is=0, and because $t_1=0$, $\&_{58}$ is=0 and therefore $A_3=0$.

(134) Because $A_3=0$, $\&_{52}$ is=0, because $H_2=0$, $\&_{53}$ is=0 and therefore $H_3=0$.

(135) Due to the return of $H_3=0$, $\&_{53}$ is=0, because $t_2=0$, $\&_{52}$ is=0 and therefore $H_3=0$.

65 After this counting step, each of the main and auxiliary storage units puts out—as indeed each unit should—a 0. As the overlapping of the partial signals shows, there are no discontinuities.

70 *Counting backward with the binary counters*

The non-presettable as well as the presettable counter is able to count backwards. Upon erasing ($1=L$) the outputs A of the counter stages are set to 0 and the outputs $\bar{A}$ are set to L (compare, for example, FIGURE 5 and

FIGURE 15). The outputs A thus indicate the number $\alpha=0 \dots 00$ while the outputs $\bar{A}$ indicate the number $\beta=L \dots LL$. After presetting to a number γ , the outputs A indicate the number $\alpha'=\alpha+\gamma$ while the outputs $\bar{A}$ indicate the number $\beta'=\beta-\gamma$. With each counting step, the number α or α' is increased by one, while the number β or β' is decreased by one. The pulse diagram in FIGURES 2a and 2b show the condition of the counter without there being any presetting, while the pulse diagram of FIGURES 13a and 13b shows the condition for the preset counter.

Erasing of the counter which forms a part of an arrangement

When a counter is used as one component of an electronic system which uses further storage units, it may be that the storage units of this counter are to be erased independently of the other storage units of the system which do not form any part of these counters. In that case, the erasing signal for the counters, indicated, above, by 1, can be made up of two signals. If, for example, all of the storage units of the system, including the storage unit of the counters, are to be erased with a signal $1_1=L$, but if with a further signal $1_2=L$ only those storage units which belong to the counters are to be erased, there can be formed an erasing signal

$$1_1 \vee 1_2 = l \quad (42)$$

whereupon, depending on the arrangement of the storage units, 1 or $\bar{1}$ is applied to the storage units of the counters while 1_1 or $\bar{1}_1$ is applied to the other storage units of the system.

Counting signals and auxiliary counting signals

In the synthesis of the switching functions for the counter it has initially been assumed that the counting signals and auxiliary counting signals appear at spaced time intervals, as shown in section a of FIGURE 1. Other forms for the auxiliary counting signals are possible. Section b of FIGURE 1 shows, for example, auxiliary counting signals t_2 which appear within the counting signals t_1 . In this case, the signals t_2 can be used as counting signals and the signals $\bar{t}_1$ as auxiliary counting signals. Section c of FIGURE 1 shows overlapping counting and auxiliary counting signals. In this case, the counting signal can be, for example, $(t_1 \& \bar{t}_2)$ and the auxiliary counting signal can be $(t_2 \& \bar{t}_1)$. The signals t_1 , $\bar{t}_1$, t_2 , $\bar{t}_2$, can in accordance with above, be combined with each other in separate circuits arranged exteriorly of the counter proper, or the counter stages can be provided with additional inputs, that is to say, the AND-circuits can be provided with an input for t_1 (or t_2) and a further input for $\bar{t}_2$ (or $\bar{t}_1$).

Conversion to a decimal counter

The above described embodiments of the binary counter can readily be modified so that they will operate as decimal counters.

Inasmuch as each counter stage can assume two states (0 or L), a decimal counter requires at least four counter stages per decade. Only ten out of the sixteen possible combinations which the four counter stages can put out are used, so that six combinations have to be omitted. The ten combinations which are selected from the sixteen will be those which allow the decimal counter to have as simple a switching function as possible. A particularly advantageous arrangement is one in which the counter puts out the decimal number in the form of a natural binary code. FIGURE 17a shows a pulse diagram for such a decimal counter which may, for example, be arranged as shown in FIGURE 18. The significance of the signals t_1 , t_2 , 1 and z_2 has already been explained. The signals put out by the main storage units S_A of the counter stages are again indicated at A, while the signals put out by the auxiliary storage units S_H are indicated at H. In the case of the signals A and H, the upper index refers

to the decade (value 10^0 , $10^1 \dots$) while the lower index refers to the particular stage within the decade (value 2^0 , $2^1 \dots$). The signal A_3^0 , for example, thus has the value $2^3 \cdot 10^0 = 8$. The main and auxiliary storage units of the respective stage within the decade are similarly referenced. The decimal counter according to FIGURE 18 will be described below. It will be seen that the signals A_0^0 to A_3^0 of the first four stages according to the pulse diagram of FIGURE 17a correspond, as far as the vertical line w_1 , to the signals A_0 to A_3 of the binary counter whose operation is shown in the pulse diagram of FIGURE 2a.

As is shown in the pulse diagram of FIGURE 17a, it is essential that, in the case of the decimal counter and in contradistinction to the operation of the binary counter, the following must occur with the next step (beginning with the counting signal c_{10}): the output A_1^0 has to remain 0 (the output A_1 of the binary counter becomes L at this point), the output A_3^0 has to change from L to 0 (the output A_3 of the binary counter remains L at this point), and the signal at output A_0^1 has to equal L (the output A_4 of the binary counter still remains 0 at this point). From this point on, the four counter stages of the decimal counter for the first decade start again to count from 0, 1, 2 $\dots$, until the point marked in the pulse diagram with the vertical line w_2 is reached, whereupon any other cycle will have been completed, one cycle comprising ten counted positions. The same applies for the counter stages pertaining to the succeeding decades.

The pulse diagram of FIGURE 17a shows the signals A_0^0 to A_3^0 and A_0^1 to A_3^1 , as well as the signals H_0^0 to H_3^0 and H_0^1 to H_3^1 put out by the counter stages of the first two decades up to the 23rd counting step, due consideration having been given to the fact that the counting was interrupted twice ($z_2=0$).

The manner in which switching function of the binary counter is, in accordance with the present invention, changed in order to obtain a decimal counter, is explained with reference to the binary counter of FIGURE 6.

The switching functions for the first four counter stages of this binary counter remain, for now, unchanged, the equations, however, being given with the notation pertaining to the decimal counter (compare functions (29), (30), (32), (10)):

$$(t_1 \& z_2 \& \bar{H}_0^0) v(A_0^0 \& \bar{H}_0^0 \& \bar{1}) v(A_0^0 \& \bar{t}_1') = A_0^0 \quad (43)$$

$$(t_1 \& H_0^0 \& \bar{H}_1^0) v(A_1^0 \& \bar{H}_1^0 \& \bar{1}) v(A_1^0 \& \bar{t}_1') = A_1^0 \quad (44)$$

$$(t_1 \& H_1^0 \& \bar{H}_2^0) v(A_2^0 \& \bar{H}_2^0 \& \bar{1}) v(A_2^0 \& \bar{t}_1') = A_2^0 \quad (45)$$

$$(t_1 \& H_2^0 \& \bar{H}_3^0) v(A_3^0 \& \bar{H}_3^0 \& \bar{1}) v(A_3^0 \& \bar{t}_1') = A_3^0 \quad (46)$$

where

$$(\bar{t}_1 \& \bar{1}) = \bar{t}_1' \quad (31)$$

$$(t_2 \& A_0^0) v(H_0^0 \& e) = H_0^0 \quad (47)$$

$$(t_2 \& A_1^0) v(H_1^0 \& H_0^0) = H_1^0 \quad (48)$$

$$(t_2 \& A_2^0) v(H_2^0 \& H_1^0) = H_2^0 \quad (49)$$

$$(t_2 \& A_3^0) v(H_3^0 \& H_2^0) = H_3^0 \quad (50)$$

where

$$(z_2 \& A_0^0) v(z_2 \& \bar{t}_2) = e \quad (33)$$

As is apparent from the pulse diagrams of FIGURES 2a and 17a, the signals of the first counter stage of the binary and decimal counters, namely, A_0^0 and A_0 as well as H_0^0 and H_0 , are the same. The first counter stage of the binary counter can thus be used, without change, for the decimal counter.

In order that, as is necessary for the decimal counter, A_1^0 does not become L at the point w_1 (see pulse diagram for FIGURE 17a), the first bracket of the switching function for A_1^0 (Equation 44) is changed to produce the desired result. What can be done is either (a) to add a suitable blocking signal to the mentioned term for the response condition, or (b) the signal H_1^0 can be made to equal L for the duration of the counting signal $t_1(c_{10})$,

as indicated by the block b_3 which, in FIGURE 17a, is drawn in dashed lines.

In case (a), H_1^0 remains equal to 0 at place marked by w_1 (in this case, there is no block b_3), so that neither A_2^0 nor H_2^0 can become equal to L. Output A_3^0 is already L and is to become 0 at this point of discontinuity; this is brought about most simply by the block b_5 (i.e., the signal $H_3^0=L$ for the duration of the counting signal t_1 (c_{10}), in consequence of which $\bar{H}_3^0$ appearing in the first and second bracket for the switching function of A_3^0 is =0). Inasmuch as in case (a) the block b_4 does not appear, H_2^0 in the second bracket of the switching function for H_3^0 (Equation 50) is replaced by H_0^0 , so as to read

$$(H_0^0 \& H_0^0) \quad (51)$$

thereby to produce the block b_5 . The thus-produced block b_5 can serve as the mentioned blocking condition for the appearance of A_1^0 , i.e., the switching function for A_1^0 (Equation 44) has to be so changed that A_1^0 cannot become L if $H_3^0=L$. The first bracket for the response condition for A_1^0 (Equation 44) thus becomes

$$(t_1 \& H_0^0 \& \bar{H}_1^0 \& \bar{H}_3^0) \quad (52)$$

In the case (b) it is the block b_3 which is produced. The signal A_2^0 must then be prevented from becoming equal to L at the point w_1 . This can be effected by producing the block b_7 . (Not taken into consideration here is the case where a blocking signal is added to the switching function for A_2^0 (Equation 45) inasmuch as this possibility can—as already described—be put to better use with the counter stage A_1^0 .) The block b_5 appears as the result of block b_4 , without there being any change in the switching function for H_3^0 (Equation 50), in consequence of which A_3^0 is erased at w_1 . In order to form the blocks b_3 and b_4 , an additional term of the setting condition, namely,

$$v(A_3^0 \& A_0^0 \& t_2) \quad (53)$$

is added to the switching function for H_1^0 (Equation 48) as well as to the switching function for H_2^0 (Equation 49). Inasmuch as H_3^0 is set by $(t_2 \& A_3^0)$ independently of H_1^0 and H_2^0 , the additional term can be simplified to

$$v(H_3^0 \& A_0^0) \quad (54)$$

The switching functions for the counter stages of the next decade, having the value 10^4 are obtained—without the necessary changes, for the time being—from the functions (43) to (50), by replacing, in each instance, the upper index 0 by 1, by replacing z_2 by H_3^0 in function (43), and by replacing e by H_3^0 in function (47). There is thus obtained:

$$(t_1 \& H_3^0 \& H_0^1) v(A_0^1 \& \bar{H}_0^1 \& \bar{I}) v(A_0^1 \& \bar{t}_1') = A_0^1 \quad (55)$$

$$(t_1 \& H_0^1 \& H_1^1) v(A_1^1 \& \bar{H}_1^1 \& \bar{I}) v(A_1^1 \& \bar{t}_1') = A_1^1 \quad (56)$$

$$(t_1 \& H_1^1 \& H_2^1) v(A_2^1 \& \bar{H}_2^1 \& \bar{I}) v(A_2^1 \& \bar{t}_1') = A_2^1 \quad (57)$$

$$(t_1 \& H_2^1 \& H_3^1) v(A_3^1 \& \bar{H}_3^1 \& \bar{I}) v(A_3^1 \& \bar{t}_1') = A_3^1 \quad (58)$$

$$(t_2 \& A_0^1) v(H_0^1 \& H_3^0) = H_0^1 \quad (59)$$

$$(t_2 \& A_1^1) v(H_1^1 \& H_0^1) = H_1^1 \quad (60)$$

$$(t_2 \& A_2^1) v(H_2^1 \& H_1^1) = H_2^1 \quad (61)$$

$$(t_2 \& A_3^1) v(H_3^1 \& H_2^1) = H_3^1 \quad (62)$$

After the counter stages of the second decade (value 10^4) have completed a cycle of ten counting positions, i.e., upon the change-over of the count from 99 to 100, these stages are to start counting again beginning with 0. By considering the counter stages of the second decade in a manner analogous to that in which the counter stages of the first decade were considered, it will be seen that, in the solution corresponding to the case (a), the first bracket of the function (56) for A_1^1 , has to be changed to

$$(t_1 \& H_0^1 \& \bar{H}_1^1 \& \bar{H}_3^1) \quad (63)$$

and the second bracket in function (62) for H_3^1 has to be changed to

$$(H_3^1 \& H_3^0) \quad (64)$$

or, in the solution corresponding to case (b), the switching functions (60) and (61) for H_1^1 and H_2^1 have to have added to them the additional setting condition represented by the term

$$v(t_2 \& A_0^0 \& A_3^0 \& A_0^1 \& A_3^1) \quad (65)$$

or the term

$$v(H_3^0 \& A_0^0 \& A_0^1 \& A_3^1) \quad (66)$$

The switching functions for the next, higher order decades (10^2 , 10^3 , and so on) are obtained in a similar manner.

The circuitry required for a decimal counter making use of (b) is more elaborate than that required for a decimal counter making use of (a). In the case (b), the number of inputs of the additional components is increased by 2 per decade; for example, the additional component for H_1^2 and H_1^3 of the third decade has added to it inputs A_0^2 and A_3^2 . The solution (b), which is characterized by the fact that, in the pulse diagram of FIGURE 17a, the blocks b_3 , b_4 , b_8 , b_9 appear, can be simplified to a solution (c) by adding the term

$$v(A_3^1 \& t_2) \quad (67)$$

$i=0, 1, 2 \dots$ to the switching functions for H_1^i and H_2^i instead of the above terms (65), (66). In solution (c), there will also appear the blocks b_6 , b_7 , b_{10} , b_{11} , shown in FIGURE 17a in dashed lines, which, however, do not disturb the counting operation.

For the sake of understandability, the switching functions for the first two decades of a decimal counter, developed from the binary counter of FIGURE 6, are shown below, both in the light of solution (a) and solution (c).

Solution (a)

$$(t_1 \& z_2 \& H_0^0) v(A_0^0 \& \bar{H}_0^0 \& \bar{I}) v(A_0^0 \& \bar{t}_1') = A_0^0 \quad (68)$$

$$(i \& H_0^0 \& \bar{H}_1^0 \& \bar{H}_3^0) v(A_1^0 \& \bar{H}_1^0 \& \bar{I}) v(A_1^0 \& \bar{t}_1') = A_1^0 \quad (69)$$

$$(t_1 \& H_1^0 \& \bar{H}_2^0) v(A_2^0 \& \bar{H}_2^0 \& \bar{I}) v(A_2^0 \& \bar{t}_1') = A_2^0 \quad (70)$$

$$(t_1 \& H_2^0 \& \bar{H}_3^0) v(A_3^0 \& \bar{H}_3^0 \& \bar{I}) v(A_3^0 \& \bar{t}_1') = A_3^0 \quad (71)$$

$$(t_1 \& H_3^0 \& \bar{H}_0^1) v(A_0^1 \& \bar{H}_0^1 \& \bar{I}) v(A_0^1 \& \bar{t}_1') = A_0^1 \quad (72)$$

$$(t_1 \& H_0^1 \& \bar{H}_1^1) v(A_1^1 \& \bar{H}_1^1 \& \bar{I}) v(A_1^1 \& \bar{t}_1') = A_1^1 \quad (73)$$

$$(t_1 \& H_1^1 \& \bar{H}_2^1) v(A_2^1 \& \bar{H}_2^1 \& \bar{I}) v(A_2^1 \& \bar{t}_1') = A_2^1 \quad (74)$$

$$(t_1 \& H_2^1 \& \bar{H}_3^1) v(A_3^1 \& \bar{H}_3^1 \& \bar{I}) v(A_3^1 \& \bar{t}_1') = A_3^1 \quad (75)$$

where

$$\bar{t}_1 \& \bar{I} = \bar{t}_1' \quad (31)$$

$$(t_2 \& A_0^0) v(H_0^0 \& e) = H_0^0 \quad (76)$$

$$(t_2 \& A_1^0) v(H_1^0 \& H_0^0) = H_1^0 \quad (77)$$

$$(t_2 \& A_2^0) v(H_2^0 \& H_0^0) = H_2^0 \quad (78)$$

$$(t_2 \& A_3^0) v(H_3^0 \& H_0^0) = H_3^0 \quad (79)$$

$$(t_2 \& A_0^1) v(H_0^1 \& H_3^0) = H_0^1 \quad (80)$$

$$(t_2 \& A_1^1) v(H_1^1 \& H_0^1) = H_1^1 \quad (81)$$

$$(t_2 \& A_2^1) v(H_2^1 \& H_1^1) = H_2^1 \quad (82)$$

$$(t_2 \& A_3^1) v(H_3^1 \& H_2^1) = H_3^1 \quad (83)$$

$$(z_2 \& A_0^0) v(z_2 \& \bar{t}_2) = e \quad (33)$$

Solution (c)

$$(t_1 \& z_2 \& H_0^0) v(A_0^0 \& \bar{H}_0^0 \& \bar{I}) v(A_0^0 \& \bar{t}_1') = A_0^0 \quad (84)$$

$$(t_1 \& H_0^0 \& \bar{H}_1^0) v(A_1^0 \& \bar{H}_1^0 \& \bar{I}) v(A_1^0 \& \bar{t}_1') = A_1^0 \quad (85)$$

$$(t_1 \& H_1^0 \& \bar{H}_2^0) v(A_2^0 \& \bar{H}_2^0 \& \bar{I}) v(A_2^0 \& \bar{t}_1') = A_2^0 \quad (86)$$

$$(t_1 \& H_2^0 \& \bar{H}_3^0) v(A_3^0 \& \bar{H}_3^0 \& \bar{I}) v(A_3^0 \& \bar{t}_1') = A_3^0 \quad (87)$$

$$(t_1 \& H_3^0 \& \bar{H}_0^1) v(A_0^1 \& \bar{H}_0^1 \& \bar{I}) v(A_0^1 \& \bar{t}_1') = A_0^1 \quad (88)$$

$$(t_1 \& H_0^1 \& \bar{H}_1^1) v(A_1^1 \& \bar{H}_1^1 \& \bar{I}) v(A_1^1 \& \bar{t}_1') = A_1^1 \quad (89)$$

$$(t_1 \& H_1^1 \& \bar{H}_2^1) v(A_2^1 \& \bar{H}_2^1 \& \bar{I}) v(A_2^1 \& \bar{t}_1') = A_2^1 \quad (90)$$

$$(t_1 \& H_2^1 \& \bar{H}_3^1) v(A_3^1 \& \bar{H}_3^1 \& \bar{I}) v(A_3^1 \& \bar{t}_1') = A_3^1 \quad (91)$$

where

$$\bar{t}_1 \& \bar{I} = \bar{t}_1' \quad (31)$$

$$(t_2 \& A_0^0) v(H_0^0 \& e) = H_0^0 \quad (92)$$

$$(t_2 \& A_1^0) v(H_1^0 \& H_0^0) v(A_3^0 \& t_2) = H_1^0 \quad (93)$$

$$(t_2 \& A_2^0) v(H_2^0 \& H_1^0) v(A_3^0 \& t_2) = H_2^0 \quad (94)$$

$$(t_2 \& A_3^0) v(H_3^0 \& H_2^0) = H_3^0 \quad (95)$$

25

$$(t_2 \& A_0^1) v(H_0^1 \& H_3^0) = H_0^1 \quad (96)$$

$$(t_2 \& A_1^1) v(H_1^1 \& H_0^1) v(A_3^1 \& t_2) = H_1^1 \quad (97)$$

$$(t_2^1 \& A_2^1) v(H_2^1 \& H_1^1) v(A_3^1 \& t_2) = H_2^1 \quad (98)$$

$$(t_2 \& A_3^1) v(H_3^1 \& H_2^1) = H_3^1 \quad (99)$$

where

$$(z_2 \& A_0^0) v(z_2 \& t_2) = e \quad (33)$$

The switching function for the $(i+1)$ th decade having the value 10^i is apparent from the switching function for the second decade (10^1), the upper index 1 in each case being replaced by i .

FIGURE 18 shows, for example, the first decade of a non-presettable decimal counter operating according to functions (84) to (87) and (92) to (95), which correspond to the above-described solution (c). The counter was developed from the binary counter of FIGURE 6. The same components, i.e., the parts of the binary counter which are taken over by the decimal counter without any modification, are identified by the same reference characters.

It will be seen that the structure and control of the main storage units $S_{A_0^0}$ to $S_{A_3^0}$ as well as the auxiliary storage units $S_{H_0^0}$ to $S_{H_3^0}$ shown in FIGURE 18 correspond to the structure and control of the storage units of the binary counter according to FIGURE 6. In order to convert the binary counter into the decimal counter, all that is necessary, as a comparison between FIGURES 6 and 18 will show, is that the auxiliary storage units $S_{H_1^0}$, $S_{H_2^0}$ of FIGURE 18 are each provided with a further input AND-circuit $\&_{90}$, $\&_{91}$, which the comparable auxiliary storage units S_{H_1} , S_{H_2} of FIGURE 6 do not have. Both of these additional circuits are controlled by the auxiliary counting signal t_2 and the output signal A_3^0 of the main storage unit $S_{A_3^0}$. The AND-circuit $\&_{90}$ and the AND-circuits $\&_{32}$, $\&_{33}$ control the OR/NOT-circuit v_{34a} , while the AND-circuits $\&_{91}$, $\&_{42}$, $\&_{43}$ control the OR/NOT-circuit v_{44a} . The circuits v_{34a} , v_{44a} , have one more input than do their counterparts v_{34} , v_{44} , in FIGURE 6. It will be appreciated, therefore, that very little additional circuitry is needed to convert the binary counter into a decimal counter.

The counter stages of a decimal counter according to solution (a) as well as those according to solution (c), which are enlarged with respect to the counter stages of the binary counter, can be so modified as to be constituted of a first part which is similar to the other stages and a second, supplemental part.

In case (a), for example, the switching functions (69) and (73) become

$$(t_1 \& P_1^0 \& \bar{H}_1^0) v(A_1^0 \& \bar{H}_1^0 \& \bar{I}) v(A_1^0 \& \bar{t}_1') = A_1^0 \quad (101)$$

$$(t_1 \& P_1^1 \& \bar{H}_1^1) v(A_1^1 \& \bar{H}_1^1 \& \bar{I}) v(A_1^1 \& \bar{t}_1') = A_1^1 \quad (102)$$

where

$$(H_0^0 \& \bar{H}_3^0) = P_0^0 \quad (103)$$

or

$$\bar{H}_0^0 v H_3^0 = P_0^0 \quad (105)$$

and

$$(H_0^1 \& \bar{H}_3^1) = P_0^1 \quad (104)$$

or

$$\bar{H}_0^1 v H_3^1 = P_0^1 \quad (106)$$

In case (c), for example, the switching functions (93), (94), (97) and (98) become

$$(t_2 \& q_1^0) v(H_1^0 \& H_0^0) = H_1^0 \quad (107)$$

$$(t_2 \& q_2^0) v(H_2^0 \& H_1^0) = H_2^0 \quad (108)$$

$$(t_2 \& q_1^1) v(H_1^1 \& H_0^1) = H_1^1 \quad (109)$$

$$(t_2 \& q_2^1) v(H_2^1 \& H_1^1) = H_2^1 \quad (110)$$

where

26

$$(A_1^0 v A_3^0) = q_1^0$$

(111)

$$\bar{A}_1^0 \& \bar{A}_3^0 = q_1^0 \quad (115)$$

$$(A_2^0 v A_3^0) = q_2^0 \quad (112)$$

(112)

$$\bar{A}_2^0 \& \bar{A}_3^0 = q_2^0 \quad (116)$$

(116)

$$(A_1^1 v A_3^1) = q_1^1 \quad (113)$$

(113)

$$\bar{A}_1^1 \& \bar{A}_3^1 = q_1^1 \quad (117)$$

(117)

$$(A_2^1 v A_3^1) = q_2^1 \quad (114)$$

(114)

$$\bar{A}_2^1 \& \bar{A}_3^1 = q_2^1 \quad (118)$$

(118)

FIGURE 19 shows, by way of example, the first decade of a non-presettable decimal counter operating according to functions (84) to (87), (92), (107), (108), (95), which correspond to solution (c). All of the counter stages of this counter are similarly constructed.

The components which are similar to comparable components of the counter of FIGURE 6 are again identified by the same reference characters. The counter of FIGURE 19 differs from that of FIGURE 18 in that the AND-circuits $\&_{90}$, $\&_{91}$, are omitted; furthermore, a change has been made in the control of the input AND-circuit $\&_{32a}$ of the auxiliary storage unit $S_{H_1^0}$ and the input AND-circuit $\&_{42a}$ of the auxiliary storage unit $S_{H_2^0}$, which two last-mentioned AND-circuits replace the AND-circuits $\&_{32}$, $\&_{42}$ of the counter of FIGURE 6. The control by the output signal A of the corresponding main storage unit is replaced by the signals q_1^0 (AND-circuit $\&_{32a}$) and q_2^0 (AND-circuit $\&_{42a}$).

FIGURE 20 shows an arrangement for forming the signals q used in the counter according to FIGURE 19 (compare the functions (115) to (118)). This arrangement comprises two AND/NOT-circuits $\&_{100}$ and $\&_{101}$ which are controlled by signals $\bar{A}_1^1$, $\bar{A}_3^1$, $\bar{A}_2^1$, $\bar{A}_3^1$, respectively. The signal q_1^1 appears at the output of circuit $\&_{100}$ while the signal q_2^1 appears at the output of circuit $\&_{101}$.

By means of the above arrangement, the other embodiments of the binary counter can also be converted into decimal counters.

Presetting the decimal counters

The manner in which the binary counters are to be modified in order that they may be preset has already been described. Similarly, the decimal counters according to the present invention can be modified to enable them to be preset to a given decimal number. The switching function for A_i^1 then has a term

$$v(f \& k_i^1) \quad (100)$$

added to it, k_i^1 being a preset signal having the value $2^i \cdot 10^i$.

FIGURE 21 shows a pulse diagram of a presettable decimal counter. The significance of the signals has already been explained. The blocks, drawn in dashed lines at the signals H_1^0 , H_2^0 , H_1^1 and H_2^1 appear only in a decimal counter according to solution (c), but not in the case of a decimal counter according to solution (a).

FIGURE 22 shows, for example, the solution (a) for the first decade of a presettable decimal counter according to functions (68) to (71), and (76) to (79), the switching function having been expanded, for A_i^1 , by the term $v(f \& k_i^1)$.

The counter of FIGURE 22 corresponds to the presettable binary counter of FIGURE 15, components of the same construction and controlled in the same way being once again identified by the same reference numerals. The counter of FIGURE 22 differs from that of FIGURE 15 in that the AND-circuits $\&_{53}$ and $\&_{38}$ are replaced by AND-circuits $\&_{53a}$ and $\&_{38a}$. The AND-circuit $\&_{53a}$ of auxiliary storage unit S_{H3^0} is controlled, not by the output signal of the auxiliary storage unit of the preceding stage, but by the output signal of the auxiliary storage unit S_{H0^0} of the first counter stage of the decade. The AND-circuit $\&_{38a}$ of the main storage unit S_{A1^0} has, as compared to the corresponding AND-circuit $\&_{38}$ of the counter of FIGURE 15, an additional input which is connected to the output of the OR/NOT-circuit v_{54} of the auxiliary storage unit S_{H0^0} of the fourth counter stage of the decade. The additional circuitry for converting the counter from a binary to a decimal counter in accordance with solution (a) is also minimal.

FIGURE 23 shows, by way of example, the first decade of a presettable decimal counter, according to solution (a), operating according to the functions (68), (101), (70) to (75), the switching functions for A_i^i having been expanded by the term $v(j \& k_i^i)$ and all of the main and auxiliary storage units of the counter stages being constructed alike. The components of the counter according to FIGURE 23 have the same structure and are controlled in the same manner as the components of the counter of FIGURE 22, the same reference characters again being used to identify corresponding components, except as follows: there is an input AND-circuit $\&_{38b}$ with three inputs for the main storage unit S_{A1^0} which replaces the AND-circuit $\&_{38a}$. Two control signals for the AND-circuit $\&_{38b}$ of FIGURE 22 (the signals H_3^0 and H_0^0) are combined into a separate circuit and the output signal P_1^i of this circuit is applied to one input of the AND-circuit $\&_{38b}$.

FIGURES 24a and 24b show circuit arrangements for forming the signals P used in the counter of FIGURE 23 (compare functions (103) to (106)). The circuit arrangement of FIGURE 24a comprises an AND/NOT-circuit $\&_{102}$ whose output is connected to a NOT-circuit 103, at whose output appears the signal P_0^i . The circuit $\&_{102}$ is controlled by the signals H_0^i and H_3^i . The arrangement according to FIGURE 24b, which produces the signal P_0^i , comprises an OR/NOT-circuit v_{104} which is controlled by the signals H_0^i and H_3^i .

Backward counting of the decimal counters

The decimal counters can easily and economically be modified so as to enable them to count backward. If, for example, the outputs A of the four counter stages of a decade indicate 00L0, corresponding to the decimal number 2, the outputs $\bar{A}$ indicate LL0L, i.e., decimal 13, which is the complement of 15. For counting backwards, however, four outputs are required—hereinafter identified by B—which put out the complement to 9.

FIGURE 25 contains a Table 1 showing six counting steps 1 to 6, the counting results appearing at the outputs A of two decades with the value 10^0 , 10^1 , the combination appearing at the outputs $\bar{A}$, as well as the results which are to appear at the outputs B. Table 2 shows all of the possible combinations which may appear at the outputs A of a decade, together with the corresponding combinations of the outputs B. The signals B are to be formed from the signals A and $\bar{A}$. The following applies:

$$A_0^i = B_0^i \quad (119)$$

$$A_1^i = B_1^i \quad (120)$$

$$(A_1^i \& A_2^i) v (\bar{A}_1^i \& A_2^i) = B_2^i \quad (121)$$

or

$$(A_1^i \& A_2^i) v (\bar{A}_1^i \& \bar{A}_2^i) = B_2^i \quad (123)$$

$$\bar{A}_1^i \& \bar{A}_2^i \& \bar{A}_3^i = B_3^i \quad (122)$$

or

$$A_1^i v A_2^i v A_3^i = B_3^i \quad (124)$$

It will be seen that the signals B_0^i and B_1^i need not be produced specially. FIGURE 26 shows a circuit arrangement for forming the signal B_2^i , while FIGURES 27a and 27b show circuit arrangements for forming the signal B_3^i . The arrangement according to FIGURE 26 comprises two AND-circuits $\&_{105}$, $\&_{106}$, whose outputs are connected to an OR/NOT-circuit v_{107} . The AND-circuit $\&_{105}$ is controlled by the signals A_1^i and A_2^i , while the AND-circuit $\&_{106}$ is controlled by the signals $\bar{A}_1^i$ and $\bar{A}_2^i$. The signal B_2^i appears at the output of the OR/NOT-circuit v_{107} . The arrangement shown in FIGURE 27a comprises an AND/NOT-circuit $\&_{108}$ whose output is connected to a NOT-circuit 109. The AND/NOT-circuit $\&_{108}$ is controlled by the signals $\bar{A}_1^i$, $\bar{A}_2^i$, $\bar{A}_3^i$. The signals B_3^i appears at the output of the NOT-circuit 109. The arrangement shown in FIGURE 27b comprises an OR/NOT-circuit v_{110} which is controlled by the signals A_1^i , A_2^i , A_3^i , the signal B_3^i appearing at the output of circuit v_{110} .

After erasing, the outputs A of the decimal counter indicate the number $\alpha = 0000 \dots 0000 0000$ (written decadically as 0 . . . 00), the outputs B indicate the number $\beta = L00L \dots L00L L00L$ (written decadically as 9 . . . 99). After presetting a number γ , the outputs A indicate the number $\alpha' = \alpha + \gamma$ while the outputs B indicate the number $\beta' = \alpha - \gamma$. With each counting step the number α or α' is increased by one unit while the number β or β' is decreased by one unit.

In the pulse diagram of FIGURE 17b, the signals B of the first two decades are shown for 23 counting steps, as derived from the switching functions (119) to (124).

Decoding for the indication by the decimal counters

When the signals taken from the outputs A or $\bar{A}$ of the binary counter are to be indicated, the result appears as a natural binary number. In similar manner, the signals A or B of the decimal counter deliver the result of the count as a decimal number whose digits appear in natural binary code (there being, for example, four lamps or other indicators for each decade).

If, in the case of a decimal counter, the result of the counting operation is to be indicated by a single lamp, a suitable converter will be required. In this case, each decade will have ten lamps, one for each of the digits 0 to 9. The signal which, during forward counting, is to control the indicating element for the decimal number ν of the $(i+1)$ th decade is identified by α_i^i or $\bar{\alpha}_i^i$. The following are two particularly advantageous logical switching functions for the binary to decimal converter.

$$\begin{aligned} \bar{A}_3^i \& \bar{A}_2^i \& \bar{A}_1^i \& \bar{A}_0^i = \alpha_0^i \\ \bar{A}_3^i \& \bar{A}_2^i \& \bar{A}_1^i \& A_0^i = \alpha_1^i \\ \bar{A}_2^i \& A_1^i \& \bar{A}_0^i = \alpha_2^i \\ \bar{A}_2^i \& A_1^i \& A_0^i = \alpha_3^i \\ A_2^i \& \bar{A}_1^i \& \bar{A}_0^i = \alpha_4^i \\ A_2^i \& \bar{A}_1^i \& A_0^i = \alpha_5^i \\ A_2^i \& A_1^i \& \bar{A}_0^i = \alpha_6^i \\ A_2^i \& A_1^i \& A_0^i = \alpha_7^i \\ A_3^i \& \bar{A}_0^i = \alpha_8^i \\ A_3^i \& A_0^i = \alpha_9^i \end{aligned} \quad (125)$$

$$\begin{aligned} A_3^i v A_2^i v A_1^i v A_0^i = \bar{\alpha}_0^i \\ A_3^i v A_2^i v A_1^i v \bar{A}_0^i = \bar{\alpha}_1^i \\ A_2^i v A_1^i v \bar{A}_0^i = \alpha_2^i \\ A_2^i v A_1^i v \bar{A}_0^i = \bar{\alpha}_3^i \\ \bar{A}_2^i v A_1^i v A_0^i = \bar{\alpha}_4^i \\ \bar{A}_2^i v A_1^i v \bar{A}_0^i = \alpha_5^i \\ \bar{A}_2^i v \bar{A}_1^i v A_0^i = \alpha_6^i \\ \bar{A}_2^i v \bar{A}_1^i v \bar{A}_0^i = \alpha_7^i \\ \bar{A}_3^i v A_0^i = \bar{\alpha}_8^i \\ \bar{A}_3^i v \bar{A}_0^i = \alpha_9^i \end{aligned} \quad (126)$$

Converters operating according to the above functions require very few components.

FIGURE 28a shows a circuit arrangement operating according to the functions (125) while FIGURE 28b shows a converter operating according to functions (126). The matrix of FIGURE 28a comprises AND/NOT-circuits &₁₂₀ to &₁₂₉, which are controlled by the signals A₀ⁱ, A₁ⁱ A₂ⁱ, A₃ⁱ, and the negated signals $\bar{A}_0^i$, $\bar{A}_1^i$, $\bar{A}_2^i$, $\bar{A}_3^i$. Signals α_0^i , to α_6^i can be taken off the outputs of these circuits. The matrix of FIGURE 28b comprises OR/NOT-circuits v₁₃₀ to v₁₃₉ which are controlled by the same signals and which put out signals α_0^i to α_6^i . Which of the two converters is to be used will depend on whether the indicating elements are actuated by an L or by a 0 signal.

Similary, the β_1^i or β_2^i are the signals which control the indicating elements during backward counting of the counter. In order to produce the signals β , a converter similar to those described above for producing the α signals can be used. In functions (125) and (126), A has to be replaced by B and α by β . The β signals can also be derived directly from the A signals; in that case α_1^i is, in the functions (125) and (126), replaced by β_6^i — (e.g., α_2^i is replaced by β_7^i , α_0^i is replaced by β_3^i , and so on).

Alternatively, the output combinations of the signals of the counter stage of each decade can be converted into signal combinations which control luminous elements arranged to form numerals. FIGURE 29a shows, schematically, the arrangement of seven luminous elements δ_1^i , to δ_7^i . If these luminous elements are controlled in a certain way, by signals δ_1^i to δ_7^i , there may be obtained a luminous representation of the numerals 0 to 9 as shown in FIGURE 29b. The table in FIGURE 29c shows the output combinations of a decade, under A₀ⁱ to A₃ⁱ, which control a converter, to be described below. The desired output combinations for this converter, i.e., the combination of luminous elements which are to be energized to produce the numerals which correspond to the binary code put out by A₀ⁱ to A₃ⁱ, are set forth under columns δ_1^i to δ_7^i .

The following are particularly advantageous logical functions for the converter:

$$\begin{aligned}
 & (A_2^i \& \bar{A}_1^i \& \bar{A}_0^i) v(\bar{A}_3^i \& \bar{A}_2^i \& \bar{A}_1^i \& A_0^i) = \bar{\delta}_1^i \\
 & (\bar{A}_3^i \& A_2^i \& \bar{A}_1^i) v(A_2^i \& A_1^i \& A_0^i) = \bar{\delta}_2^i \\
 & (A_2^i \& A_1^i \& \bar{A}_0^i) v(A_2^i \& A_1^i \& A_0^i) v(\bar{A}_3^i \& \bar{A}_2^i \& \bar{A}_1^i \& A_0^i) = \bar{\delta}_3^i \\
 & (\bar{A}_2^i \& A_1^i) v(A_1^i \& A_0^i) v(\bar{A}_3^i \& \bar{A}_2^i \& A_0^i) = \bar{\delta}_4^i \\
 & (A_2^i \& \bar{A}_1^i \& A_0^i) v(A_2^i \& A_1^i \& A_0^i) = \bar{\delta}_5^i \\

Converters operating according to the above switching functions can be made to use very simple circuitry. FIGURE 30a shows a converter operating according to the switching functions (127) while FIGURE 30b shows a converter operating according to the switching functions (128).

The converter of FIGURE 30a comprises input AND-circuits &₂₀₁ to &₂₁₅ which are controlled by the signals A₀ⁱ to A₂ⁱ as well as $\bar{A}_0^i$ to $\bar{A}_3^i$, the first fourteen of these AND-circuits controlling, in pairs, OR/NOT-circuits v₂₁₆ to v₂₂₁, while the fifteenth AND-circuit &₂₁₅ controls a NOT-circuit 222, the signals δ_1^i to δ_7^i appear-

ing at the outputs of the circuits v₂₁₆ to v₂₂₁ and 222, respectively.

The converter according to FIGURE 30b comprises input AND-circuits &₂₂₃ to &₂₄₇ which are controlled by signals A₀ⁱ to A₃ⁱ and $\bar{A}_0^i$ to $\bar{A}_3^i$, the outputs of these AND-circuits being connected to OR/NOT-circuits v₂₄₈ to v₂₅₄, as shown in the drawing, at whose outputs appear the signals δ_1^i to δ_7^i .

Which of the two converters is to be used will depend on whether the luminous elements δ_1^i to δ_7^i respond to an L signal or to a 0 signal.

Error control for the decimal counters

The outputs of the decimal counters put out, in the (i+1)th decade, the signals A₀ⁱ to A₃ⁱ. FIGURE 31a shows all of the possible combinations within one decade. But in practice, the counter should put out only those combinations which correspond to decimal numbers 0 to 9. Accordingly, means are provided for producing an error signal $\epsilon^i = L$ in the event one of the other six combinations, i.e., one of the combinations representing the decimal numbers 10 to 15 is put out, and FIGURES 31b and 31c show circuit arrangements for producing the error signals ϵ^i and $\bar{\epsilon}^i$, respectively, these arrangements operating, respectively, according to the functions

$$(A_1^i \& A_3^i) v (A_2^i \& A_3^i) = \epsilon^i \tag{129}$$

$$(\bar{A}_3^i) v (\bar{A}_1^i \& \bar{A}_2^i) = \bar{\epsilon}^i \tag{130}$$

The arrangement shown in FIGURE 31b comprises two AND-circuits &₂₆₁ and &₂₆₂ controlled by signals A₁ⁱ, A₃ⁱ; A₃ⁱ, A₂ⁱ, respectively. The outputs of the two AND-circuits are connected to an OR/NOT-circuit v₂₆₃ at whose output the error signal ϵ^i appears.

The arrangement shown in FIGURE 31c comprises two AND-circuits &₂₆₄ and &₂₆₅ controlled by signals A₁ⁱ, A₂ⁱ, A₃ⁱ, the outputs of the two AND-circuits being connected to an OR/NOT-circuit v₂₆₆ at whose output the error signal ϵ^i appears.

Summary

It will be seen from the above that the present invention resides, basically, in a multiple-digit counter having a counter stage for each digit, each counter stage comprising means for applying counting signals, means for applying auxiliary counting signals which are staggered with respect to the counting signals, a bistable main storage unit at whose output appears the count of the respective digit, and means for controlling the instants at which the main storage unit is set and erased, the controlling means incorporating a bistable auxiliary storage unit which has different circuit conditions at these two instants, and at least one of the following: the counter stage of the preceding digit, the mentioned means for applying the counting signals, and the mentioned means for applying the auxiliary counting signals.

The counter is, basically, a binary counter capable of counting forward and backward and is susceptible, or not, as desired, to being preset. The counter is, however, readily modifiable into a decimal counter which itself is susceptible, or not, as desired, to being preset. The counter is controlled by the counting signals and the auxiliary counting signals of any desired shape, which auxiliary counting signals appear at spaced time intervals with respect to the counting signals.

Additionally, suitable indicating means and error checking means are provided, as described above.

It will be understood that the above description of the present invention is susceptible to various modifications, changes, and adaptations, and the same are intended to be comprehended within the meaning and range of equivalents of the appended claims.

What is claimed is:

1. A multiple-digit counter having a counter stage for each digit, each counter stage comprising:
  - (a) means for applying counting signals;
  - (b) means for applying auxiliary counting signals which are staggered with respect to and timely spaced from the counting signals;
  - (c) a bistable main storage unit at whose output appears the count of the respective digit; and
  - (d) means for controlling the instants at which said main storage unit is set and erased, said controlling means incorporating:
    - (1) a bistable auxiliary storage unit which has different circuit conditions at said two instants, and
    - (2) at least one of the following: the counter stage of the preceding digit, said means for applying the counting signals, and said means for applying said auxiliary counting signals.
2. A counter as defined in claim 1, wherein, during the counter operation, the main storage unit of each binary digit changes its circuit condition only at the instant of a counting signal, and wherein the corresponding auxiliary storage unit changes its circuit condition only at the instant of an auxiliary counting signal or a counting signal but not at the same instant as said main storage unit.
3. A counter as defined in claim 1 wherein said auxiliary storage unit has at least two input AND-circuits and said main storage unit has at least three input AND-circuits, the input AND-circuits of each storage unit being connected to a respective OR/NOT-circuit, each of said OR/NOT-circuits having its output connected to a respective NOT-circuit whose output, in turn, constitutes the output of the respective storage unit.
4. A counter as defined in claim 1 wherein the auxiliary storage unit of the lowest order binary digit forms signals for controlling the main storage unit of the same binary digit in dependence on the count (0 or L) of the main storage unit of the same binary digit, and the auxiliary storage unit of the higher order digits forms signals for controlling the main storage unit of the same binary digit and the main and auxiliary storage units of the next higher binary digit, in dependence on the count of the main storage unit of the same binary digit and the count of the auxiliary storage unit of the next lower binary digit, such that the respective main storage units form, with the help of such signals, signal combinations which correspond to the selected binary code.
5. A counter as defined in claim 1, further comprising means for applying a counting command signal z to the counter stage of the lowest order, thereby to control whether the counter is to carry out its counting operation.
6. A counter as defined in claim 5 wherein said means for applying said counting command signal to said counter stage of the lowest order also produces a clear for counting signal z_2 , said clear for counting signal being derived from said counting command signal z and being so synchronized as to appear and disappear with the beginning of an auxiliary counting signal.
7. A counter as defined in claim 1 wherein the counter stages of all of the digits, except the counter stage of the lowest order digit, are of similar construction, and wherein the counter stage of the lowest order digit is composed of two parts one of which is of the same construction as the counter stages of the remaining digits and the other of which is an input part.
8. A counter as defined in claim 1, further comprising a combining circuit to which said means for applying said counting signals and said auxiliary counting signals apply these signals, the output of said combining circuit replacing said counting and auxiliary counting signals.
9. A counter as defined in claim 1, said counter being presetable and further comprising means for applying presetting signals to said main storage units after

an erasing signal has been applied to said counter, said presetting signals disappearing prior to the commencement of the counting operating.

10. A counter as defined in claim 9 wherein said last-mentioned means comprise a logic circuit associated with each respective main storage unit, means for applying a presetting signal k to said logic circuit, and means for applying a clear for presetting signal f to said logic circuit.
11. A counter as defined in claim 10 wherein said clear for presetting signal f appears after the erasing signal $1=L$, and disappears with the appearance of the clear for counting signal $z_2=L$, not to reappear until a further erasing signal $1=L$ has appeared.
12. A counter as defined in claim 1 and modified to serve as a decimal counter, said counter incorporating a plurality of decades each incorporating four binary stages, and connecting means incorporating one of the following: (1) means for applying the output signal of the fourth stage to the second and third stages and (2) means for applying the output signal of the fourth stage to the second stages and means for applying the output signal of the first stage to the fourth stage.
13. A counter as defined in claim 12 wherein the signals controlling the binary counter stages are constituted by the signals required for the decimal conversion, or wherein the signals controlling the binary stages are so combined with the signals required for the decimal conversion in additional logic circuit means whose output signals constitute the signals for controlling said stage, said logic circuit means being arranged such that the constructions of said stages remains unchanged for purposes of decimal counting.
14. A counter as defined in claim 12, further comprising means for applying presetting signals k to the main storage units of said stages, thereby to enable said counter to be preset to a given decimal number.
15. A static counter capable of counting forward and backward and susceptible, or not, as desired, to being preset, said counter being, basically, a binary counter but readily modifiable into a decimal counter which it-
self is susceptible, or not, as desired, to being preset, said counter being controlled by counting signals and auxiliary counting signals of any desired shape, which auxiliary counting signals appear at spaced time intervals with respect to the counting signals, said counter comprising, for each binary digit, a main storage unit at whose output appears the count of the particular digit, and an auxiliary counting unit associated with said main storage unit; the two instants of time at which the main storage unit is set and erased being fixed by the corresponding auxiliary storing unit which, at said two instants of time, has different circuit conditions (0 or L) and by at least one counter stage of a preceding binary digit or a counting signal or an auxiliary counting signal.
16. A counter comprising, in combination: a plurality of stages, each having a main storage unit and an auxiliary storage unit; each main storage unit and the auxiliary storage unit of the lowest order stage having three input AND-circuits, an OR/NOT-circuit having three inputs connected to the outputs of the three AND-circuits, and a NOT-circuit having an input connected to the output of the OR/NOT-circuit; the auxiliary storage units of all but the lowest order stage having two input AND-circuits, an OR/NOT-circuit having two inputs connected to the outputs of the two AND-circuits, and a NOT-circuit having an input connected to the output of the OR/NOT-circuit; and means for applying control signals to said input AND-circuit, said control signal applying means including means for applying counting signals and auxiliary counting signals, the latter being staggered with respect to and timely spaced from the former.
17. A counter comprising, in combination: a plurality of stages, each having a main storage unit and an aux-

four stages, each having a main storage unit and an auxiliary storage unit; each main storage unit having four input AND-circuits, an OR/NOT-circuit having four inputs connected to the outputs of the four AND-circuits, and a NOT-circuit having an input connected to the output of the OR/NOT-circuit; each auxiliary storage unit having two input AND-circuits, an OR/NOT-circuit having two inputs connected to the outputs of the two AND-circuits, and a NOT-circuit having an input connected to the output of the OR/NOT-circuit; and means for applying control signals to said input AND-circuits, said means including a logic circuit for deriving a signal from the auxiliary storage units of the first and fourth stages and applying the same to an input of one of the four input AND-circuits of the main storage unit of the second stage, said control signal applying means further including means for applying counting signals and auxiliary count-

ing signals, the latter being staggered with respect to and timely spaced from the former.
